UNITED STATES PATENT OFFICE.

JOHN ERICKSON, OF CHICAGO, ILLINOIS, ASSIGNOR TO AUTOMATIC ELECTRIC COMPANY, OF CHICAGO, ILLINOIS, A CORPORATION OF ILLINOIS.

COMMON-BATTERY TELEPHONE-EXCHANGE TRUNKING SYSTEM.

1,284,274.

Specification of Letters Patent. Patented Nov. 12, 1918.

Application filed March 27, 1908, Serial No. 423,672. Renewed April 9, 1917. Serial No. 160,886.

To all whom it may concern:

Be it known that I, JOHN ERICKSON, a citizen of the United States of America, and resident of Chicago, Cook county, Illinois, have invented a certain new and useful Improvement in Common-Battery Telephone-Exchange Trunking Systems, of which the following is a specification.

My invention relates to telephone systems in general, but more especially to automatic or semi-automatic telephone exchange systems, and particularly to systems in which the current for talking purposes is supplied to the subscribers' stations from one or more batteries at the exchange or central station.

It will be seen that my invention is in the nature of an improvement on the system disclosed in my prior application Serial No. 249,709, filed March 13, 1905, for improvement in automatic telephone systems.

The principal object of my invention is the adaptation of the system of my said prior application to common battery work, that is to say, the combining of the essential features of said prior system with means for supplying talking current to the subscribers' lines from one or more batteries at the exchange or central station.

It is also an object, of course, to provide certain details and features of improvement and novel combinations tending to increase the general efficiency and serviceability of an automatic telephone exchange system of this particular character.

To the foregoing and other useful ends, my invention consists in matters hereinafter set forth and claimed.

In the accompanying drawings Figures 1 and 2 show diagrammatically a portion of a telephone system embodying my invention. In said figures the calling subscriber's station is shown at A, and the called subscriber's station at A'. These two substations are shown connected through the medium of automatic switches and switching mechanism. The line of the substation A is provided with a double-wound individual relay 42 and an individual bridge-cut-off coil 43. At C is shown a preliminary connector or finder switch, sometimes called a preselector. It will be understood that in the system the subscribers are divided into a number of groups. Allotted to each group of subscribers is a certain number of selec-

tors D, which are more or less a modified form of the switch disclosed in United States Letters Patent No. 815,321, granted March 18, 1906, to Keith, Erickson and Erickson. Additional selectors, as shown at E, of the same general type as D are provided, also in groups. The system also has connector switches F of the general type disclosed in Letters Patent No. 815,176, granted March 13, 1906, to Keith, Erickson and Erickson, but modified so as to adapt them to a common battery system.

Fig. 3 is a diagrammatic view illustrating the construction and circuit arrangement of the finder operating device, which is an impulse transmitter, and which is common to a group of subscribers.

Fig. 4 is a plan view of the said impulse transmitter, and also shows several of the line or individual relays.

Fig. 5 is a top end elevation of the said transmitter shown in Fig. 4.

Fig. 6 is a section on line 6—6 of Fig. 4 looking in the direction indicated by the arrows.

Fig. 7 is a detail view showing the position of some of the parts shown in Fig. 6 when the operating magnet is energized.

Fig. 8 is a detail section on line 8—8 in Fig. 5.

Fig. 9 is a horizontal section on line 6—6 in Fig. 4, but looking in a direction opposite to that indicated by the arrows.

Fig. 10 is a bottom end elevation of the said transmitter shown in Fig. 4.

Fig. 11 is a detail section on line 11—11 in Fig. 9.

Fig. 12 is a detail perspective of the interrupter shown in Fig. 9.

Fig. 13 is a detail view of one of the controlling relays 172, 190, etc., shown in Fig. 3.

Fig. 14 is a diagrammatic view illustrating the construction and circuit arrangement and bank of one of the primary connectors or finders.

The substations may be of any suitable or approved type. The substation A, in connection with which I have elected to illustrate my invention, comprises a receiver 2, and a switch-hook 3 for controlling the substation circuits, which controlling operations are accomplished through the medium of any suitable means, such as the cam arms 4, 5 and 6 on the switch-hook. As the

switch-hook is lowered the cam arm 5 momentarily presses the release springs 7, 8 and 9 into engagement, whereby the substation line conductors may be grounded simultaneously. When the switch-hook is down the cam arm 4 maintains a contact between the springs 10 and 11, thereby bridging the ringer 12 in series with the condenser 13 across the line. The substation ground circuit is normally broken between the ground springs 14 and 15 by the cam arm 6; but when said springs are together, ground circuit is provided to the ground post 17 and the release spring 7, as is usually the case in telephones of this type. The said substation also comprises the usual transmitter 18, and the induction coil 19 having the primary winding 20 and the secondary winding 21. Being an automatic substation it is provided with the usual vertical and rotary impulse springs 22 and 23. The vertical impulse spring 22 is provided with an oblique projection or lug 24 on the under side, with which lug the vertical impulse teeth 25 are adapted to engage for intermittently driving the spring 22 onto the ground post 17. The rotary impulse spring 23 is provided with a similar mechanism 26 for driving the said rotary spring onto the ground post once by means of the rotary impulse tooth 27 each time that the dial returns to normal after being rotated. Suitable means for grounding the vertical line once (when the receiver is removed) may be provided in any suitable manner, as by the lug 28 on the switch-hook 3 adapted to make contact with the lug 29 of spring 7. The number of impulses produced through the medium of the vertical impulse spring 22 is accurately and definitely determined at each operation of the dial by the finger-hole which the subscriber selects on the dial. It should be stated that a suitable stop is, as is well known, provided to always limit the rotation of the dial, which stop indicates when to release the dial. By referring to Fig. 1 it will be seen that the impulse springs 22 and 23 are electrically connected with the vertical and rotary line conductors 30 and 31 that lead to the central office. The substation is, of course, provided with a dial (not shown) which is secured to the shaft 32, together with the locking dog 33. Furthermore, there is a locking cam 34 that locks the dog 33 while the receiver is on the switch-hook to prevent rotation of the dial. Said cam, by means of the finger 35, also maintains the separation of the ground springs 14 and 15 until the dial is moved, after the receiver is removed. The vertical impulse teeth 25 and the rotary impulse tooth 27 are carried on the periphery of the impulse wheel 36 which is secured to the shaft. The said impulse teeth are so arranged that when the dial is drawn down

the impulse springs 22 and 23 are not carried into contact with the ground post 17, said contact occurring only as the impulse wheel returns to rest. In this operation the subscriber's vertical line conductor 30 is first given a number of ground impulses, and then the rotary line conductor 31 is given one ground impulse. It will be seen that as long as the dial is out of normal position the dog 33 permits the primary circuit springs 37 and 38 to separate, thus preventing the impulses that are delivered to either line conductor from passing to the other. The means whereby the subscriber may signal the called subscriber comprises the push-button spring 39 which normally engages the contact point 40; but when the button 41 is pressed the spring 39 engages the contact point 42, whereby the vertical line conductor 30 may be grounded. The line relay 42 (Fig. 1) may consist of any suitable double-wound coil equipped with switching contact springs such as 44, 45 and 46. Likewise, the bridge-cut-off relay 43 may be any suitable wound coil equipped with normally closed contact springs such as 47, 48 and 49. Said line and bridge-cut-off coils may, of course, be placed in any convenient or advantageous position as, for example, on a relay rack of suitable construction.

The central transmitting mechanism is set in operation by the line switching relay 42. Referring particularly to Fig. 4, it will be seen that said mechanism consists of a suitable frame or body 50 adapted to provide bearings and supports for the various operative parts and magnets. For example, the shaft 51 which carries the wiper 52 is supported in the bearing 53. It is also provided with a ratchet wheel 54 adapted to be operated by the pawl 55 pivotally mounted on the armature 56 of the rotary magnet 57. Referring to Fig. 9 it will be seen that the pawl is limited in its forward thrust or movement by an adjustable stop-screw 58 inserted through the part 59 of the said body frame. A spring locking dog 60 also engages the ratchet wheel and thereby prevents a backward rotation of the shaft 51. The pawl 55 is pivoted at 61 to the upper end of the armature arm 62 and is subject to suitable spring tension for holding it in engagement with the ratchet teeth. The said armature 56 is provided with a spring 63 so applied that the said armature is normally away from the magnet 57. This spring also constitutes the means for actuating the ratchet device, the pawl being attracted when the magnet is energized, and the ratchet wheel rotated when the arm is released. The spring wiper 64 is adapted to describe a circle as it slides over the contact teeth or switch contacts, which latter are arranged in a circle, as illustrated.

These contacts are each provided with a terminal 65 for making the necessary connections with the conductors leading to the contacts of the vertical and rotary relays. 5 The said spring wiper is preferably secured to an insulated hub 66 (Fig. 4) on the shaft 51, said hub being engaged by a brush or spring arm 67. With this arrangement it will be seen that the conductor 68 (Fig. 3) 10 can be secured to the terminal of the brush 67, and that in this way the necessary current from ground to battery B is conveyed through the wiper 52 without including the shaft 51 in the circuit. The armature 56 15 also carries the insulated interrupter arm 69, which latter is adapted to operate the opening and closing of springs 70 and 71. This interrupter is of the character disclosed in United States Letters Patent No. 20 831,875, granted September 25, 1906, to A. E. Keith. The said interrupter arm is provided at its end with a lateral projection 72 adapted, when the arm is attracted, to first engage the intermediate spring 73, 25 and to then pass between the spring and the outer portion of the spring 70. In so doing it presses the outer end of the spring 71 out of engagement with the end of the spring 70, a piece of insulation separating 30 the springs 73 and 71. When the armature is released the finger 72 again passes between the ends of the springs 73 and 70, thereby preventing the springs 70 and 71 from reengaging each other until after the 35 armature has been completely restored to its normal position. It will be understood, however, that any other suitable, known or approved arrangement can be employed for producing an intermittent energizing of the 40 rotary magnet 57. The cam 74 mounted upon the shaft 51 may be made of hard rubber or other suitable insulating material. With the arrangement shown this cam is substantially round in character, being provided with only a single projection or node 75, as shown in Fig. 10. This projection or node normally engages the spring 76 for the purpose of keeping the springs 76 and 77, and likewise the springs 79 and 80, nor 50 mally separated, as shown in Figs. 3 and 10. It will be also be observed that the springs 76 and 78 are normally in engagement. The cam 74 rotates in a forward direction and, after releasing the said springs, makes a 55 complete rotation in unison with the wiper 64 before again engaging the said springs and returning the latter to their normal condition. Again referring to Fig. 4 it will be seen that the shaft 81 is supported on 60 bearings 82 and preferably arranged parallel with the shaft 51. The spring wipers 83, 84 and 85 are all mounted upon the shaft 81 and (as shown more clearly in Fig. 8) are all insulated from each other 65 and from the said shaft. It is understood, of course, that these wipers revolve in unison with the said shaft. The vertical bank contacts of the vertical wiper 85 are provided with terminals 86, the rotary bank contacts of the rotary wiper 84 with terminals 70 87, and the private bank contacts of the private wiper 83 with terminals 88. These vertical, rotary and private bank contacts are arranged in the manner shown more clearly in Fig. 5 and are, of course, 75 all insulated from each other. This bank is formed on the arc of a circle and is removable as a unit. Consequently the said wipers 83, 84 and 85 are preferably double-ended, so to speak, each wiper being provided with opposite ends adapted to engage and travel upon its allotted contacts. In this way each wiper is adapted to revolve in a forward direction, and with one end reengage its allotted series or row of contacts immediately after disengaging the last contact in such row or series with the opposite end. In other words, the opposite ends of each wiper are alternately brought into engagement with the contacts, the arrangement being such, however, that while one end is in use the other end is not. The wiper 85 (Fig. 8) is insulated from the shaft and from the other wipers, but is in electrical contact with the metal hub or 80 collar 89. In this way a brush or spring contact 90, which bears upon the said hub or collar, is employed for furnishing current to the said wiper. The arrangement of the other two wipers is practically the 85 same, the wiper 84 being provided with a hub or collar 91 and a brush or spring contact arm 92, and the private wiper 83 is provided with a hub or collar 93 engaged by a brush or spring arm 94. As previously 90 explained, these wipers 83, 84 and 85 all rest upon contacts of the semi-circular bank 95, and consequently the wipers of the switch are always in electrical connection 95 with a trunk-line (either busy or non-busy) 100 and with the preliminary connector at the end of such line. The motive power or propelling means for rotating the shaft 81 consists of the rotary magnet 96, the armature 97, the pawl 98 and the ratchet wheel 105 99. The said armature is suitably mounted and pivoted at 100, and the said pawl is pivotally secured at 101 to the upwardly-projecting arm of said armature. A spring 110 102 (Fig. 6) of any suitable character is employed for keeping the pawl fixed against the teeth of the ratchet wheel. An adjustable stop-screw 103 limits the forward thrust or movement of the said pawl, while a spring locking dog 104 engages the 115 ratchet wheel and thereby prevents backward rotation of the shaft upon which the latter is secured. A spring 105 (Fig. 6) is suitably applied to keep the said armature 97 normally away from the core or pole 120 106 125 130.

piece of the magnet 96. This armature 97 is provided with an interrupter arm 106 adapted to manipulate or operate the circuit opening and closing springs 107 and 108. The construction and arrangement of these springs, and the operation of the said interrupter arm, are identical with the construction and mode of operation of the circuit-breaker or interrupter allotted to the magnet 57. Consequently no further description of the magnet 96 need be given. In Fig. 4 it will be observed that the switch-operating machine comprising the automatic calling switch shaft 51 and the automatic trunk selector switch shaft 81, is mounted on a suitable support. Said machine also has a relay 180 which controls one switch point in the circuit of the rotary magnet 57. Connections to the contacts of the wiper 52 are controlled by the double-wound relays 172, 190, etc., Fig. 3, of which those situated to the left of the line Y—X are known as the rotary relays, and those to the right as the vertical relays. In Fig. 13 a detailed and amplified illustration of the construction of these relays is shown for the purpose of more clearly bringing out the arrangement of the windings, and of the normally closed contacts controlled by said relays. It is to be understood that this construction may be employed for all of said vertical and rotary relays.

The preliminary connector or finder C (Fig. 1), sometimes called a trunk connector, is a modification of the connector switch disclosed in said Letters Patent No. 815,176, and is provided with the usual vertical and rotary magnets 111 and 112, the release magnet 113, and the release relay 114. One of the differences that may be noted is that it lacks the usual line relays.

The selector switch D, as already stated, is a modified form of a well-known selector switch. It is provided with a vertical magnet 115, a rotary magnet 116, a release magnet 117 and a private magnet 118. The said private magnet, of course, controls the side switch wipers 119, 120, 121 and 122 and also the circuit of the vertical magnet 115, in the usual manner, by means of the springs 123 and 124. Included in the energizing circuit of the rotary magnet are the usual interrupter springs 125. The operative magnets of the switch are controlled by the subscriber through the medium of the vertical and rotary relays 126 and 127, as is customary. Said relays have under their control the usual springs 128, 129 and 130, and also the trunk-release springs 131 and 132. By means of the back-release relay 133 the release of the switch D is brought about after the side switch has passed to third position.

The selector E (Fig. 2), as in the case of the selector D, is provided with the vertical

and rotary magnets 134 and 135, the release magnet 136 and the private magnet 137, which latter controls the vertical magnet through the springs 138 and 139. As usual, the private magnet likewise controls the side switch wipers 147, 148, 149 and 150. The line relays 140 and 141 control the operative magnets through the springs 142, 143 and 144. The said relays acting conjointly press the release spring 145 and 146 into contact, the former of which is connected with the release magnet 136, and the latter with the trunk-release conductor, thus closing an energizing circuit through the said magnet. The back-release relay 151 enables the switch to be released after the side switch has reached the third position.

In the connector switch F the vertical and rotary line relays 152 and 153^a may be operated to impart to the shaft wipers 153, 154 and 155 their vertical and rotary motions. While the side switch is in first position the vertical line relay 152 controls the vertical magnet 156. When the side switch passes to second position the same relay controls the rotary magnet 157. Similarly, when the side switch passes to third position the ringer relay 158 is in turn controlled by the relay 152. The connector rotary line relay 153^a, as usual, controls the private magnet 159, which latter in turn operates to shift the side switch wipers 160, 161, 162 and 163 from first to second position, and from second to third position. The two line relays acting conjointly provide means whereby the release magnet 164 may be energized to release the connector switch. The differential relay 165 controls the energizing circuit of the back-bridge relay 166, through which latter the called subscriber receives battery current for talking purposes. The said relay 166, upon energizing, closes a circuit which in turn provides the calling subscriber with battery current for conversation.

The exchange or central office is also provided with the usual busy-signaling machine M and a suitable ringer generator R.

Station A, it will be understood, is, for the purpose of illustrating my invention, considered as one of a group of one hundred telephones. It will likewise be understood that these one-hundred stations may be part of a one-thousand group comprised in an exchange of ten-thousand subscribers, as, for example, the second hundred of the second thousand group, in which case the numbers will vary from the smallest number 2200 to 2299. It will also be seen that in Fig. 3 eighty-one stations are indicated by the three contact springs corresponding to the contact springs 44, 45 and 46 for each telephone subscriber's station already mentioned, it being understood that a line relay 130

is associated with each of these eighty-one sets of contacts, such as the relay 42. Furthermore, it will be seen that the relays 167 and 171, and those between these two 5 relays, constitute what may be called the vertical relays of the switch-operating machine, inasmuch as they control the different circuits over which the vertical impulses are transmitted by the said machine for operating the vertical magnets of the preliminary connectors. On the other hand, the relays 172 and 173, and all of the relays between these two particular double-wound relays, constitute what may be called the rotary relays of the switch-operating machine, inasmuch as these particular relays control the different circuits over which the said machine transmits the rotary impulses for operating the rotary magnets of the preliminary 10 connectors. Consequently, the nine relays to the right of the line X-Y control the tens digits of the numbers of the subscribers in this particular group, while all of the relays to the left of said line control the units digits of the said numbers—that is to say, determine the impulses for such digits. For example, if subscriber #2211 takes down his receiver, the result of such act would be the energizing of relays 172 and 167—that is to say, of the inner coils of these two relays. In such case the switch-operating machine will be allowed by the relay 172 to send first only one impulse on the vertical side and then one on the rotary side, and by relay 167 to send in only one impulse on the vertical side again and one on the rotary side, thereby in effect calling his own station. Again, should subscriber #2299 remove his receiver from the 15 switch-hook, the result would be the energizing of relays 173 and 171, and in this case the switch-operating machine will first transmit nine impulses on the vertical side and one on the rotary side to the idle or waiting preliminary connector, and then nine on the vertical again and one on the rotary. With this arrangement the first tens relay 167 coöperates with the first units relay, or with some other relay at the left 20 of line X-Y, according to the number of the calling subscriber to find the line of the calling subscriber when the tens digit of that subscriber is one; and in like manner the second tens relay 168 coöperates with some one other relay at the left of the line X-Y, according to the number of the calling subscriber, to find a calling subscriber whose tens digit is two, etc. Invariably then if the tens digit of the calling subscriber's 25 number is five, for example, the taking down of the receiver at this subscriber's station will result in the energizing of the inner coil of the fifth tens relay 178; but if in any case the tens digit of the calling subscriber's number is eight, for example, then the

eighth tens relay will be energized. On the other hand, and invariably if the units digit of the calling subscriber's number is five, the result will be the energizing of the fifth units relay; but if the units digit is eight, for example, then the eighth units relay will be energized. In any case, however, it will be seen that the energizing of a certain tens relay, for example, makes it possible for only a certain number of the tens contacts to receive and transmit impulses from the wiper 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 eight eighth tens relay will be energized. On the other hand, and invariably if the units digit of the calling subscriber's number is five, the result will be the energizing of the fifth units relay; but if the units digit is eight, for example, then the eighth units relay will be energized. In any case, however, it will be seen that the energizing of a certain tens relay, for example, makes it possible for only a certain number of the tens contacts to receive and transmit impulses from the wiper 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905

simply removing the receiver, or in any other suitable manner, automatically calls his own line, so to speak, and thereby establishes connection with an idle trunk-line running 5 to a so-called first-selector, or to some other switch. As soon as this has been done the subscriber is then ready to begin the operation of calling the desired number. But he is only connected with the said first-selector, or other switch, from the time the preliminary connector seizes the calling line until the switches are restored to their normal positions. Thus there are no individual switches, the line relays being practically 15 the only devices which are made individual to each other. Obviously, therefore, the number of so-called first-selectors, and other necessary switches, may be considerably less in number than the total number of subscribers, with the result that the apparatus 20 is simplified and materially reduced without in any way reducing the efficiency of service between subscribers. This is, of course, largely due to the fact that the central transmitter switch (Fig. 3) after connecting the calling subscriber's line, with one of the first-selectors returns to its normal condition and remains in readiness for use by another subscriber of the same group. With 25 this arrangement, therefore, the switch shown in Fig. 3 is always in readiness to be employed by any subscriber of the group for the purpose of connecting his line with an idle first-selector. Thus, notwithstanding 30 the fact that there are no step-by-step selective switches which are individual to the subscribers, the operation, as far as the calling subscriber is concerned, is practically the same as if each line terminated 35 in a so-called first-selector or other similar switch. In other words, the calling subscriber, by simply removing his receiver from the usual switch-hook, automatically starts a train of electrical steps or operations 40 which are completed by the time he is ready to begin calling the desired number. By 45 this means, without any hesitation or additional work on the part of the calling subscriber, a first-selector, a second-selector, and 50 a connector or other switch, according to the size of the exchange, are thus placed in electrical connection with the line and in readiness to receive the impulse or impulses corresponding to one or more digits, as the case 55 may be, of the called number. From this point on the apparatus and the operation may be of any suitable, known or approved character, my invention relating more particularly to that part of the operation which 60 is included between the time of the taking down of the receiver of the calling subscriber and the consequent automatic connection with an idle first-selector or other switch. The devices used from then on for 65 calling the desired number, and for com-

pleting the connection through to the called subscriber's line, may be of any suitable, known or approved character.

We will assume that the subscriber at station A (Fig. 1), whose number is 2251, desires to converse with the subscriber at station A', it being assumed that the latter's number is 2299; and also, as a matter of convenience of illustration, that the two subscribers belong to the same group to which the previously mentioned switch-operating machine is allotted. It will be understood, of course, that station A' may belong to any one of the other groups of which the exchange consists. With the arrangement 70 shown, however, subscriber 2251, in removing his receiver from the switch-hook 3, will thereby produce a momentary engagement of the switch-hook projection 28 with the switch contact 29. This, it will be seen, momentarily grounds the subscriber's line conductor 30, the circuit thus momentarily formed extending from ground G' through the co-operating ground springs 14 and 15 to the contact point 29, thence to the contact 80 point 28, switch-hook 3, over conductor 174, vertical line conductor 30 to the relay 42, springs 48 and 47 and to battery lead 219, thence through battery B to ground G. In this way the removal of the receiver momentarily grounds one side of the calling subscriber's line, with the result that the relay 42, which is normally bridged across the subscriber's line, is energized sufficiently to attract the armature 176. This relay 42 is 85 normally connected by the contact springs 47, 48 and 49 with the non-grounded pole of the battery B. In other words, the momentary grounding of the subscriber's line completes a temporary circuit including the coil 42 and the battery B. When thus energized the subscriber's line relay 42, by attracting the armature 176, causes the normally separated contacts 44, 45 and 46 to be brought 90 into engagement with each other, it being 95 seen that contact 46 is connected to ground (Fig. 3). This, it will be seen, completes a circuit from ground through contact 44, conductor 177 to the relay coil 178, thence over conductor 179, contact spring 78, contact 100 spring 76, relay coil 180, conductor 181, and through battery B to ground G. In this way the energizing of the subscriber's line relay is instantly followed by the energizing 105 of the inner relay coil 178, causing the 110 relay to attract its armature, and by the energizing of relay 180 which also attracts its armature. Simultaneously with the formation of these circuits and the energizing 115 of these relays, however, another circuit is 120 closed from ground through contact arm 45 to conductor 182, thence over inner relay coil 172, over conductor 179, through contact springs 78 and 76, through relay coil 180 and over the conductor 181, to battery B 125 130

and thence to ground G. Obviously, with the arrangement shown, the inner relay coil 172, when energized, will cause the armature 183 to break contact with the contact point 184. Likewise, the inner relay coil 178, when energized as described, attracts its armature 185, thereby causing the latter to break contact with the contact point 186. At the same time the energizing of the relay 10 coil 180 will cause its armature to engage the contact point 187, thus closing a circuit as follows: from battery B through conductor 181, contact 187, armature 188, rotary magnet coil 57, thence through the normally energizing circuit-breaking contact springs 70 and 71 to ground and back to battery. This 15 rotary magnet, when energized, attracts its armature 56, causing the latter to separate the contact springs 70 and 71 and thereby permitting the armature to be instantly released. As the armature 56 is alternately attracted and released, owing to the make-and-break action which it produces in the coil 57, the spring wiper 52 is given a step-by-step motion over the said contact teeth or switch contacts. The spring wiper 52, as shown in Fig. 3, is part of an electrical circuit, and as it makes the first rotary step the anode 75, which is attached to the same 20 shaft, breaks contact with the spring 76, thereby allowing the latter to in turn break contact with the spring 78 and close contact with the spring 77, at the same time allowing the contact spring 79 to make contact 25 with the spring or switch contact 80. The contact springs or arms 77 and 76, when brought together, serve to establish a circuit from ground through the relay winding 189 (which is on the same spool or magnet 30 as the coil 172), through the corresponding winding 190 on the next spool or magnet, and thence through all the corresponding coils of the other sixteen magnets shown in Fig. 1, through conductor 191, contact 35 springs 77 and 76, coil 180, conductor 181 to battery B, and thence to ground G. Preferably the windings 189 and 190, etc., throughout all of the magnets (which windings are normally connected in series) are 40 of such construction that the attractive power of their cores or pole-pieces is comparatively slight, so that the armatures 183 and 185 which, it will be remembered, are already in contact with their respective pole-pieces or magnet cores will be retained in 45 contact therewith, but none of the armatures of the other relay magnets will be attracted. The armature 188 of the relay 180 will, however, be retained in contact with its pole-piece or magnet core, thus maintaining the 50 continuity of the previously closed circuit through the rotary magnet 57 and its circuit-breaking contact springs 70 and 71. In this way the said rotary magnet will continue 55 to rotate its shaft, and thereby keep the

spring wiper 52 moving until the latter has made a complete revolution. It will be seen, of course, that the cam 75 will also make a complete revolution simultaneously with the said wiper and will, as it returns to its starting point, again make contact with contact spring 76, thus pressing the latter out of engagement with the contact spring 77 and again closing contact with the arm or spring 78. Thus is broken the circuit just described from ground through the windings 189 and 190, etc., in series through the other series relay windings, through conductor 191, contacts 77 and 76, relay coil 180, conductor 181, and through battery B to ground G. Instantly upon the breaking of the circuit the relay coil 180 will allow its armature to return to normal position, thus breaking contact between said armature 188 and the contact 187, and thereby opening the circuit through the rotary magnet 57. At the same time the said armature 183 of the relay coil 189 will return to its normal position in engagement with the contact point 184, and armature 185 of said relay 178 will return to its normal position in engagement with the contact point 186. Obviously, however, and during the time that the spring wiper 52 is making its revolution from starting point on the contact 191, certain other operations will take place, with respect to which the following preliminary explanation is made: The wipers or switch arms 83, 84 and 85 shown in Fig. 3 are diagrammatic representations of the spring wipers shown in Figs. 4 and 5. It will be seen that the ten sets of contact teeth, such as the set 203, 204 and 205, the set 206, 207 and 208, the set 209, 210 and 211, etc., are each connected with one of the ten automatic preliminary connectors shown 105 at the left in Fig. 14, and previously referred to. For convenience of illustration, only one set of these different connections is shown. The contact point 203 is shown connected with the conductor 212; contact point 204 with conductor 213; and contact point 205 with conductor 214. These three conductors lead to the so-called preliminary connector or other suitable automatic switch shown in Fig. 14. As shown, the arrangement of circuits is such that the spring wipers 83, 84 and 85 will never rest (except for a brief instant) on a set of contacts connected with a preliminary connector which is busy or already in use. The circuits and means 110 which prevent these wipers from stopping on a set of busy contacts are as follows: Suppose, for example, that these wipers 83, 84 and 85 should for any reason whatever be moved about and so adjusted that the wiper 83 would engage the contact point 125 203, wiper 84 engage with contact 204, and wiper 85 engage with contact 205, it being understood that these three contacts constitute one of the ten sets of contacts involved 130

in the construction of the bank of switch contacts shown in Fig. 5, and also assume, for the purpose of this illustration, that the preliminary connector C (Fig. 1) connected with these three bank contacts should be found busy. In such case the spring contact arm 215 of the said preliminary connector will rest against the contact point 216, thus closing connection between ground and contact 203 by means of conductor 212, and thereby establishing a guarding potential at the contact point 203, by reason of its temporary connection with the grounded pole of the battery. Consequently, when the wiper 83 engages the contact point 203, a circuit will be closed from ground G² through conductor 212, through contact point 203, spring wiper 83, conductor 218, contact springs 108 and 107, and through the coil 96 to battery B, and thence to ground G. This will cause the rotary magnet coil 96 to attract its armature, and by means already described induce the shaft to which the spring wipers 83, 84 and 85 are attached to instantly make one rotary step, thereby carrying these wipers out of contact with points 203, 204 and 205 and into contact with the points 206, 207 and 208. If these last-mentioned bank contacts should be found busy, then the operations just described would be instantly repeated, so as to carry the spring wipers to another position. However, in order that a better understanding of the circuits may be had, it may be assumed that when the operator or subscriber at telephone 2251 starts to make the call, thus causing the spring wiper 52 to make a complete revolution over its contact points, as already described, the wiper 83 is at such time resting upon the contact point 203, wiper 84 on contact 204, and wiper 85 on contact point 205; and that the preliminary connector switch C is in its normal position, ready to receive a call from the switch-operating machine shown in Fig. 3. If these conditions prevail at the time the calling subscriber takes down his receiver, then the following operations will take place: It will be remembered that when the spring wiper 52 moves from the contact point 191, the cam 75 then moves away from the contact spring 76, thereby permitting the contact spring 79 to engage the contact arm 80. As soon as this occurs a circuit will be closed from ground through the contact arm 80, contact spring 79, conductor 217, rotary magnet 96, through battery B and then to ground G. This, of course, will cause the rotary magnet 96 to attract its armature and to retain the latter in its attracted position until the spring wiper 52 has completed its revolution, thus permitting the cam 75 to again come into contact with the spring 76 and thereby open the circuit between the springs 79 and 80. When this takes place the rotary magnet 96 releases its armature,

and by means of the pawl and ratchet device already described the spring wipers 83, 84 and 85 will be moved forward one step and onto contact points 206, 207 and 208, so as to be ready for the next call sent in from the switch-operating machine. These wipers will, however, remain on contacts 203, 204 and 205 during the time that the spring wiper 52 is making its revolution. Obviously, as the spring wiper 52 is given a step-by-step motion over its contact points 191, 192, 193, 194, 195, etc., throughout the sets of contacts in the bank and just at the time when it rests on each new contact point, it is connected to ground through the conductor 68, contact spring 70 and contact spring 71. This, it will be seen, is for the reason that whenever the wiper 52 rests on a contact point the armature 56 is away from the core or pole-piece of its magnet; and each time that the armature 56 is drawn up against its core or pole-piece, contact is thereby broken between the springs 70 and 71, the result being that the contact arm or wiper 52, as it is stepped over its teeth, will also momentarily be connected to ground as it rests on each tooth in its path of travel. The effect of this action will be readily understood, for as the contact arm or wiper 52 rests on the contact point 192 a circuit will thereby be closed from ground through the contact spring 71, contact spring 70, conductor 68, contact arm or wiper 52, contact point 192, conductor 218, vertical switch wiper 85, contact point 205, conductor 214, vertical magnet 111 to the battery lead 219, thence through battery B to ground G. The closure of this circuit results, of course, in the sending of one impulse through the vertical magnet 111, causing the latter to raise the shaft of the switch C one step. The switch wiper 52, of course, passes onto the contact 193, where it again closes a circuit and sends another impulse through the vertical magnet 111 of the said preliminary connector switch C. This latter circuit is from ground through the wiper 52, contact point 193, conductor 220, contact point 221, contact armature 222, conductor 223, conductors 218 and 224, switch wiper 85, contact point 203, thence through conductor 214 to the vertical magnet 111 of the switch C and to battery B. At such time the spring wiper 52 passes onto the contact point 194, where it effects the transmission of another impulse through the vertical magnet 111, the circuit at this time being closed through the contact point 194, conductor 225, contact point 226, armature 227, contact point 221, armature 222, conductor 223, conductors 218 and 224 to the vertical wiper 85, etc. In this way, as the wiper 52 passes onto the contact point 195, another electrical impulse is transmitted through the vertical magnet 111. This time the circuit 125, 130, 135, 140, 145, 150, 155, 160, 165, 170, 175, 180, 185, 190, 195, 200, 205, 210, 215, 220, 225, 230, 235, 240, 245, 250, 255, 260, 265, 270, 275, 280, 285, 290, 295, 300, 305, 310, 315, 320, 325, 330, 335, 340, 345, 350, 355, 360, 365, 370, 375, 380, 385, 390, 395, 400, 405, 410, 415, 420, 425, 430, 435, 440, 445, 450, 455, 460, 465, 470, 475, 480, 485, 490, 495, 500, 505, 510, 515, 520, 525, 530, 535, 540, 545, 550, 555, 560, 565, 570, 575, 580, 585, 590, 595, 600, 605, 610, 615, 620, 625, 630, 635, 640, 645, 650, 655, 660, 665, 670, 675, 680, 685, 690, 695, 700, 705, 710, 715, 720, 725, 730, 735, 740, 745, 750, 755, 760, 765, 770, 775, 780, 785, 790, 795, 800, 805, 810, 815, 820, 825, 830, 835, 840, 845, 850, 855, 860, 865, 870, 875, 880, 885, 890, 895, 900, 905, 910, 915, 920, 925, 930, 935, 940, 945, 950, 955, 960, 965, 970, 975, 980, 985, 990, 995, 1000, 1005, 1010, 1015, 1020, 1025, 1030, 1035, 1040, 1045, 1050, 1055, 1060, 1065, 1070, 1075, 1080, 1085, 1090, 1095, 1100, 1105, 1110, 1115, 1120, 1125, 1130, 1135, 1140, 1145, 1150, 1155, 1160, 1165, 1170, 1175, 1180, 1185, 1190, 1195, 1200, 1205, 1210, 1215, 1220, 1225, 1230, 1235, 1240, 1245, 1250, 1255, 1260, 1265, 1270, 1275, 1280, 1285, 1290, 1295, 1300, 1305, 1310, 1315, 1320, 1325, 1330, 1335, 1340, 1345, 1350, 1355, 1360, 1365, 1370, 1375, 1380, 1385, 1390, 1395, 1400, 1405, 1410, 1415, 1420, 1425, 1430, 1435, 1440, 1445, 1450, 1455, 1460, 1465, 1470, 1475, 1480, 1485, 1490, 1495, 1500, 1505, 1510, 1515, 1520, 1525, 1530, 1535, 1540, 1545, 1550, 1555, 1560, 1565, 1570, 7515, 7520, 7525, 7530, 7535, 7540, 7545, 7550, 7555, 7560, 7565, 7570, 7575, 7580, 7585, 7590, 7595, 7600, 7605, 7610, 7615, 7620, 7625, 7630, 7635, 7640, 7645, 7650, 7655, 7660, 7665, 7670, 7675, 7680, 7685, 7690, 7695, 7700, 7705, 7710, 7715, 7720, 7725, 7730, 7735, 7740, 7745, 7750, 7755, 7760, 7765, 7770, 7775, 7780, 7785, 7790, 7795, 7800, 7805, 7810, 7815, 7820, 7825, 7830, 7835, 7840, 7845, 7850, 7855, 7860, 7865, 7870, 7875, 7880, 7885, 7890, 7895, 7900, 7905, 7910, 7915, 7920, 7925, 7930, 7935, 7940, 7945, 7950, 7955, 7960, 7965, 7970, 7975, 7980, 7985, 7990, 7995, 8000, 8005, 8010, 8015, 8020, 8025, 8030, 8035, 8040, 8045, 8050, 8055, 8060, 8065, 8070, 8075, 8080, 8085, 8090, 8095, 8100, 8105, 8110, 8115, 8120, 8125, 8130, 8135, 8140, 8145, 8150, 8155, 8160, 8165, 8170, 8175, 8180, 8185, 8190, 8195, 8200, 8205, 8210, 8215, 8220, 8225, 8230, 8235, 8240, 8245, 8250, 8255, 8260, 8265, 8270, 8275, 8280, 8285, 8290, 8295, 8300, 8305, 8310, 8315, 8320, 8325, 8330, 8335, 8340, 8345, 8350, 8355, 8360, 8365, 8370, 8375, 8380, 8385, 8390, 8395, 8400, 8405, 8410, 8415, 84

the contact point 195, conductor 227, contact point 228, armature 229, contact point 226, armature 227, contact 221, armature 222, conductors 223, 218 and 224, vertical wiper 85, etc. The spring wiper 52 moves onto the contact point 196, where it again effects the transmission of an electrical impulse through the contact point 196, conductor 230, contact point 231, armature 232, contact 10 point 228, armature 229, contact point 226, armature 227, contact point 221, armature 222, conductors 223, 218 and 221, vertical wiper 85, etc., it being understood that from this point on each circuit through the vertical magnet 111 is the same as the others. As stated, the spring wiper 52 moves into contact with the switch point 197, but from this point on it will not and cannot effect the transmission of another vertical impulse 20 through the vertical magnet 111. This, of course, is due to the fact that armature 185 of the coil 178 is at such time drawn up, thereby breaking contact with the contact point 186, so that the spring wiper 52 will 25 then be incapable of effecting the transmission of further vertical impulses, and will cause the transmission of no impulse or impulses of any kind whatever until it passes from the contact point 201 onto the contact point 202. When this happens it will commence to send rotary impulses over the rotary line to the rotary magnet 112 of the preliminary connector switch C. It will now be seen that five impulses, corresponding 30 to the digit in the tens place of the number of the calling subscriber, have been transmitted through the vertical magnet 111 of the preliminary connector switch C, thus raising the wipers of this preliminary connector to the proper levels—that is to say, the points of these wipers will be opposite the fifth row of contact teeth, and thus made ready for entering this level as soon as rotary impulses are sent through said rotary 35 magnet of the switch. It will be seen that, a rotary impulse is transmitted as soon as the spring wiper 52 reaches the contact point 202, a circuit being thereby momentarily closed as follows: From ground 40 through the contact spring 71, contact spring 70, conductor 68, spring wiper 52, contact point 202, conductor 233, rotary wiper 84 of the switch-operating machine, contact point 204, conductor 218, rotary magnet 112, conductor 219, through battery B to ground 45 G, thus causing a single rotary impulse to be sent through the rotary magnet 112. This causes the switch shaft of the preliminary connector to make one rotary step, placing the shaft wipers 234 and 235 in 50 contact with the switch points 237 and 238 of the bank contacts allotted to this switch, and also causing the private wiper 236 to be placed in electrical contact with the contact point 239 of a so-called private bank of 55 this switch. It will be seen that at this time the preliminary connector switch C has completed its operation, having placed the line wipers 234 and 235 on the first set of contacts of the fifth row or level in the bank of 60 line contacts, it being observed that this bank is made up of pairs of contacts, each pair consisting of two contacts connecting with the opposite sides of a subscriber's line. In other words, connection is made with the set 65 of contacts which corresponds to the last two digits of the number of the calling subscriber, thus completing the connection from the lines coming in from telephone #2251 through the conductors 240 and 241, line 70 wipers 234 and 235 to the trunk-line conductors leading to a regular first-selector, as shown in Fig. 1, or to any other suitable switching apparatus. It will be seen that at this time a circuit is also established 75 through the bridge-cut-off relay 43, this circuit being from ground through the private wiper 236, contact point 239, through relay coil 43, thence through battery B to ground 80 G, thus causing the core of the coil 43 to attract the armature 242, effecting the retention of this armature in its attracted position until the preliminary connector switch C is eventually released and restored to its normal condition after the conversation 85 has been terminated. When the bridge-cut-off relay 43 attracts its armature it breaks contact between the switch springs or contacts 47, 48 and 49, thus opening the bridge normally closed across the line conductors 30 and 31 leading from telephone 90 #2251. This bridge includes the line relay coils of the windings 242 and 243 connected normally to battery through the said contact arms. This leaves the line of the calling subscriber free from bridges of this character and puts it in condition for subscriber #2251 to operate the regular first-selector, second-selector, third-selector, etc., and the regular and usual connector. It 95 will be seen that the wiper 52, after leaving the contact point 201, passes on in the manner previously described until it again returns to the contact point 191, and at the same time the cam 74 also returns to its 100 original position, thus pressing the contact spring 76 away from the contact spring 77 and into engagement with the contact spring 78, and also breaking contact between the contact spring 79 and 80. Obviously, with 105 the arrangement shown, the contact spring 76, as it breaks away from the spring 77, serves to open the previously described circuit from ground to the coils 189 and 190, and all of the coils in series, as shown in 110 Fig. 3. This action having been accomplished, the armature 188 returns to its original position in engagement with the contact point 184, while the armature 185 of the coil 178 returns to its original post- 115 120 125 130

tion in engagement with the contact point 186. It will be seen, however, that this circuit also includes the relay coil 180, and that the latter consequently releases its armature, thereby breaking contact between the contact arm 188 and contact point 187, and in this way opening the circuit from ground through the rotary magnet coil 57. This, of course, results in bringing the 10 wiper 52 to rest on the contact point 191, where it remains until a new call is sent in from any other telephone of this particular group of subscribers. It must be borne in mind, however, that another circuit is 15 opened through the rotary magnet 96, owing to the separating of contacts 79 and 80, and consequently the magnet 96 releases its armature, whereupon the pawl of the armature 97 engages the shaft carrying the spring 20 wipers 83, 84 and 85 and thus moves the latter into engagement with the contact points 206, 207 and 208, where said wipers are ready to receive the next call coming in 25 from the calling wiper 52 in response to the removal of a telephone receiver from its hook by some other subscriber.

The method of calling the desired number is as follows: Assume, for example, that the subscriber at substation A desires to call subscriber at substation A' to which is allotted the line 2299. To call the number 2299 the subscriber at substation A raises his switch-hook and thereby automatically obtains a trunk-line which is not busy, in this case 30 trunk-line conductors 244 and 245 leading to a first-selector D. When the dial is drawn down for the first digit, then upon returning to normal position it operates the first-selector switch to establish connection 35 with an idle trunk-line leading to a second-selector E. In a similar manner, the second-selector E is operated for the second digit to select an idle trunk leading to a connector switch F. The impulses for the last 40 two digits are directed toward the connector F, which operates to place its shaft wipers in connection with the contacts corresponding to the desired line. The first digit being 2, the spring 22 is pressed against the 45 ground post 17 twice. As a result, the vertical line relay 126 of the first-selector D is energized each time by a flow of current from the substation ground G', through springs 14 and 15 to the ground post 17, 50 thence through the spring 22 to the vertical line conductor 30, conductor 240, contact point 237, line wiper 234, trunk conductor 244, side switch wiper 119, contact point 246, vertical line relay 126 to battery lead 219, thence through battery B to ground G. Each time that the vertical line relay 126 55 energizes, the line relay spring 130 is pressed onto the ground spring 129. The vertical magnet 115 is thereby energized, and the wipers 248, 249 and 250 of the selector D are 60 raised to the second bank level and brought opposite the first contact of said level. The energizing circuit for the said vertical magnet 115 extends from ground G' through the springs 129 and 130, private springs 124 70 and 123 to the vertical magnet 115, thence to the battery lead 219, and through battery B to ground G. The rotary impulse spring 23 is then pressed onto the ground post 17, grounding the rotary line conductor 31 and 75 energizing, therefore, the rotary line relay 127 of the selector D. The energizing current passes from ground G' to the rotary line conductor 31, conductor 241, contact point 238, line wiper 235, line conductor 80 245, side switch wiper 120 of the selector D, contact point 247 to the rotary line relay 127, thence to the battery lead 219, and through battery B to ground G. The rotary line relay 127, upon energizing, presses 85 the line relay spring 128 onto the ground spring 129, thereby establishing a circuit through the private magnet 118 from ground G' through the springs 129 and 128 to the private magnet 118, and through the 90 said magnet to battery lead 219, thence through battery B to ground G. The private magnet, upon energizing and deenergizing, permits the selector side switch to pass from first to second position, allowing the 95 side switch wipers 121 and 122 to engage the contact points 253 and 254, respectively. The closure of connection between the side switch wiper 121 and contact point 253 sets up an energizing circuit for the rotary magnet 116 from ground G' to the contact point 253, through the side switch wiper 121, interrupter spring 125, rotary magnet 116 to the 100 battery lead 219, thence through battery B to ground G. The said rotary magnet then 105 operates to rotate the wipers 248, 249 and 250 of the selector D into engagement with the first contact of the second level of the selector D, from which contact it is assumed that the trunk-line conductors 255, 256 and 110 257 lead to the second-selector E. If the first trunk is busy, however, and the wipers have to pass over busy trunk-lines, then as soon as the private wiper 250 engages the first grounded private bank contact point, 115 the private magnet 118 again energizes, locking the side switch in second position. Energizing circuit for said private magnet extends from the grounded terminal G of battery B through an occupying switch (not 120 shown) to the private wiper 250, thence over the conductor 259 and through the back-release relay 133 to the side switch wiper 122, contact point 254, private magnet 118, thence through said magnet to the battery lead 219, 125 and through battery B to ground G. When thus energized the private magnet 118 locks the side switch in second position and the wiper 121 in engagement with the contact point 253, thereby the rotary magnet 116 130

will be energized step by step until the wipers are carried beyond the last busy trunk-line. At the instant that the private wiper leaves the last busy contact point, the energizing circuit through the private magnet 118 is destroyed, and as a result the selector side switch passes to third position. If, however, there are no busy trunk-lines, the rotary magnet 116 releases the side switch to third position as soon as the wipers are carried into engagement with the first trunk-line. As soon as the side switch passes to third position, as stated, the subscriber's line conductors 30 and 31 are extended to the conductors 255, 256 and 257 which, in this case, it is assumed lead to the selector switch E. The extension of the line occurs, of course, as soon as the side switch wipers 119 and 120 engage the contact points 263 and 262, respectively. Not only is the subscriber's line thus extended, but a guarding potential is established at the private wiper 250, when the side switch wiper 122 passes onto the grounded contact point 262, for protecting the seized trunk-line against interference by other calling subscribers. This guarding potential is established from ground G* to the contact point 262, thence through the side switch wiper 122, through the back-release relay 133, conductor 259 to the private wiper 250. It will be seen, of course, that the energizing circuit for the rotary magnet 116 (to which reference has already been made) is destroyed when the idle trunk-line is seized—that is, when the side switch wiper 121 leaves the contact point 253. The second digit of the called member being 2, the calling subscriber again operates his dial accordingly, as a result grounding the vertical line conductor 30 when the spring 22 meets the ground post 17. The vertical line relay 141 of the switch E is, therefore, energized twice by a flow of current from the substation ground G* to the vertical line conductor 30, thence through conductor 240, contact point 237, wiper 234, conductor 244, side switch wiper 119, contact point 263, conductor 264, switch wiper 248, contact point 260, conductor 255 to the vertical line relay 141, thence to the battery lead 219, and through battery B to ground G—that is, when the vertical line conductor 30 is grounded for the second digit, an energizing circuit is established through the vertical magnet 134 which operates to carry the shaft wipers 265, 266 and 267 step by step to a position opposite the bank terminals of the second level. When the rotary line conductor 31 is grounded after the vertical impulses, the rotary line relay 140 is energized, whereby an energizing circuit is established through the private magnet 137, which in turn operates to release the side switch, as described in connection with the selector D. When the switch E comes to rest, it is assumed that the shaft wipers 265 and 266 stop in engagement with the conductors 268 and 269, respectively, as shown, whereby the calling subscriber's line conductors 30 and 31 are extended to the connector switch F. The ground impulses from the substation to the line conductors for the last two digits, namely the third and fourth, are effective in operating the connector F. The third digit is called after 70 the subscriber has established connection with the connector F by way of the trunk conductors 268 and 269. The subscriber rotates the dial as described for the third digit 9, thereby grounding the vertical and rotary 80 line conductors 30 and 31, which in turn causes the energization of the connector vertical and rotary line relays 152 and 153*, and also of the differential relay 165. The energizing current flows over the following 85 path: From ground G* to the vertical line conductor 30, trunk conductors 240, 244, 264, 255 and 268, through the winding of the vertical line relay 152 and winding 270 of the differential coil 165 to the battery lead 219, 90 thence through battery B to ground G. Each time that the vertical magnet 156 is energized it raises the shaft and wipers 153, 154 and 155 one step at a time until the said wipers are carried nine steps and brought 95 opposite the level in which are located the terminals of the line 2299. When the rotary line conductor 31 is grounded the rotary line relay 153* and the differential relay 165 become energized over the following path: 100 From ground G* to the rotary line conductor 31, trunk conductors 241, 245, 271, 256 and 269, through the winding of the rotary line relay 153* and winding 272 of the differential relay 165 to the back-bridge 105 relay springs 273 and 274 (which are normally in contact) to the battery lead 219, thence through battery B to ground G. The energization of the rotary line relay 153* causes the springs 277 and 110 278 to come into contact, thereby completing a circuit from ground G* through the private magnet 159 to the back-bridge relay springs 273 and 274, thence to the battery lead 219, and through battery B to 115 ground G. The momentary energization of the private magnet 159 causes the release of the side switch from first to second position, thus placing the side switch wipers 162 and 163 in contact with the points 279 and 120 280, respectively. The last digit being 9, the subscriber operates the dial as previously described, grounding the vertical line conductor 30 nine times and the rotary line conductor 31 once. The vertical and rotary line relays 152 and 153* are operated over the previously traced circuits. However, when the line relay springs 278 and 281 engage, a circuit is then closed through the rotary magnet 157 instead of through the 125 130

vertical magnet 156. The circuit may be traced from ground G' to the line relay springs 278 and 281, through the springs 294 and 295, side switch wiper 162, contact point 279, through the rotary magnet 157 to the battery lead 219, thence through battery B to ground G. Each time that the rotary magnet is energized the rotary armature is attracted and rotates the shaft carrying the wipers 153, 154 and 155 one step at a time, until the said wipers are carried into engagement with the normal conductors 282, 283 and 284, the first two of which lead to the line of the desired subscriber, whose number is 2299. The energization of the rotary line relay 153^a for the last digit completes an energizing circuit through the private magnet 159, which now operates with one of two results, namely the release of the side switch from second to third position, or the so-called busy-release of the connector if the called line is busy. Suppose the former result to occur and the side switch to pass to third position, thus placing the side switch wipers 160, 161, 162 and 163 in contact with the points 285, 286, 287 and 288, respectively. When the side switch wiper 162 engages the contact point 287, the ringer relay 158 comes under the control of the vertical line relay 152 in the same manner in which the rotary magnet 157 came under the control of the vertical line relay when the side switch passed from first to second position. Furthermore, when the side switch passes to third position a guarding potential is established for the protection of the called line. This guarding potential extends from ground G^{10} to the side switch wiper 163, thence to the shaft wiper 155 which now engages the private contact of the called line. The said guarding potential at the private wiper 155, furthermore, causes a flow of current to be sent through the bridge-cut-off relay 289 from the said private wiper 155 to the private normal conductor 284, to the bridge-cut-off relay 289, thence to battery lead 219, and through battery B to ground G. The said relay, upon energizing, operates to separate the springs 290, 291, and 292, which are normally closed, thus removing the battery current from the individual line relay 293 and rendering it inoperative by any impulses from the station A'.
 55 To signal the called subscriber the calling subscriber presses the signaling button 41, placing the spring 39 in contact with the substation ground G' , and thereby energizing the vertical line relay 152 from ground G' through the springs 14 and 15, contact point 42^a, spring 39, springs 37 and 38 to the vertical line conductor 30, thence over a path previously traced. When the vertical line relay 152 becomes energized the differential relay 165 is also energized through the winding

270. The armature is attracted and the springs 275 and 276 are placed in contact, thereby completing the energizing circuit extending from ground G' through the springs 277 and 281, private magnet springs 294 and 295, side switch wiper 162, contact point 287, through the ringer relay 158, differential relay springs 276 and 275 to the battery lead 219, thence through battery B to ground G. As a result the ringer relay becomes energized and its armature causes the springs 296 and 297 to make contact with the ringer generator springs 298 and 299, respectively. As a result ringing current is permitted to pass out on the line of the called subscriber, which current passes through the substation ringer 300 and signals the subscriber. This signaling current passes from the generator R to the springs 299 and 297, side switch wiper 160, contact point 285, shaft wiper 153, normal conductor 282, vertical line conductor 301, condenser 302, ringer 300, springs 304 and 305 to the rotary line conductor 306, normal conductor 283, shaft wiper 154, contact point 286, side switch wiper 161, ringer relay 158, springs 296 and 298 and back to the generator R. As soon as the calling subscriber releases his signaling button 41 the current through the vertical line relay 152 and differential relay 165 is interrupted, deenergizing the said relays, whereby the ringer relay returns to normal position. As the called subscriber removes his receiver 308 from the switch-hook 309 the latter, upon rising, destroys the ringing circuit through the bells 300 at the instant the springs 304 and 305 separate. The switch-hook, on rising, also closes the primary circuit springs 310 and 311, thus closing a circuit through its own station that provides the transmitter 312 and the primary winding 313 of the induction coil 314 with current for talking purposes. The current for this circuit passes from ground G^{10} at the connector to the side switch wiper 163, to the winding 315 of the relay 166, ringer relay springs 307 and 296 to the side switch wiper 161, rotary line wiper 154, conductors 283 and 306, primary winding 313 of the induction coil 314, transmitter 312, springs 311 and 310 to the vertical line conductor 301, conductor 282, vertical line wiper 153, side switch wiper 160 to the winding 316 of the back-bridge coil 166, springs 317 and 275 of the differential relay 165 to the battery lead 219, thence through battery B to ground G. The energizing current for the talking circuit, in passing through the coil 166, energizes said coil and causes the armature to close the springs 273 and 318 in contact. At the instant that these two springs 273 and 318 engage, the calling substation is thereby provided with current for energizing its primary talking apparatus. The circuit in this case extends from ground G^{10} to the side switch wiper 163, 130

through the springs 318 and 273, through the winding 272 of the differential relay 165, rotary line relay 153^a, trunk conductors 269, 256, 271, 245 and 241 to the rotary line conductor 31, primary winding 20 of the induction coil 19, transmitter 18, springs 37 and 38 to the vertical line conductor 30, trunk conductors 240, 244, 264, 255 and 268, vertical line relay 152, through the winding 270 of the differential relay 165, thence to the battery lead 219, and through battery B to ground G. It will be seen that the two windings 270 and 272 of the differential relay 165 are included in the circuit that provides the calling subscriber with talking current. These two windings are so arranged that when the current passes through them in this manner the differential relay 165 does not energize. Since the talking current flowing to the calling subscriber passes through the vertical and rotary line relays 152 and 153^a, these two relays, as soon as the said circuit is established, become energized and attract their respective armatures, thereby placing the trunk-release springs 319 and 320 in contact. This would result in the release of the connector were it not for the fact that the connection between the release magnet 164 and the non-grounded battery terminal 3 is interrupted between the differential relay springs 275 and 276. The primary windings 20 and 313 of the stations A and A', respectively, are now connected in series in a circuit shown in heavy lines in Figs. 1 and 2, 35 through the condensers 321 and 322 at the connector. The receivers 2 and 308 of the two substations in question are each in series in a local circuit with their respective secondary windings 21 and 322 of the induction coils 19 and 314, and the two subscribers may communicate with each other in the usual manner, since their primary circuits are charged with a suitable current from the central or common battery B, as already explained.

After the two subscribers have completed their conversation, the front release occurs when the calling subscriber restores his receiver 2 to the switch-hook 3, thereby pressing the release springs 7, 8 and 9 into engagement, which engagement places the line conductors 30 and 31 in connection with the substation ground G'. The grounding of the rotary line conductor 31 produces a cessation of the flow of current through the rotary line relay 153^a and the winding 272 of the differential relay 165. This is brought about by short-circuiting these two windings in series through ground. The short-circuit extends from ground G' to the rotary line conductor 31, trunk conductors 241, 245, 271, 256 and 269 to the rotary line relay 153^a, winding 272 of the differential relay 165 to the springs 273 and 318, to the side switch wiper 168 and to ground G¹⁰. The

rotary line relay becomes deenergized, and the trunk-release spring 319 recedes from the spring 320, and since only the winding 270 of the differential relay 165 is receiving current, the said relay becomes operatively energized. The current-flow through the said relay extends from ground G' to the release springs 7, 8 and 9, to the vertical line conductor 30, trunk conductors 240, 244, 264, 255 and 268, vertical line relay 152, winding 270 of the differential relay 165 to the battery lead 219, thence through battery B to ground G. The energization of the differential relay 165, as above, produces a deenergization of the back-bridge relay 166 when the springs 317 and 275 disengage, which relay 166, upon restoring its armature to normal position, permits the springs 273 and 318 to disengage, and the spring 273 to come in contact with the spring 274. The engagement of the springs 273 and 274 again completes an energizing circuit through the winding 272 of the differential relay 165, and in this way current passes through said winding in such a direction as to reinforce the winding 270 and, therefore, to maintain the springs 275 and 276 in contact. Simultaneously with the reenergizing of the rotary line relay 153^a of the connector, the trunk-release springs 319 and 320 engage, thus completing an energizing circuit through the release magnet 164 of the connector in series with the back-release relay 151 of the second-selector E. This circuit extends from ground G¹¹ at the selector E through the side switch wiper 150 and release relay 151, private shaft wiper 267, connector trunk-release springs 320 and 319, through the winding of the release magnet 164, differential relay springs 276 and 275 to the battery lead 219, and through battery B to ground G. The connector release magnet 164, upon energizing, operates in the usual manner to restore the shaft wipers 153, 154 and 155 and the side switch to normal position. The release relay 151 being included in the above release circuit also energizes and operates to place the springs 324 and 325 in contact, whereby a series energizing circuit is established through the back-release relay 133 of the selector D and the release magnet 136 of the selector E. This circuit extends from ground G¹² through the side switch wiper 122, release relay 133, conductor 259, private wiper 250, conductor 257, release relay springs 324 and 325, through the release magnet 136 to the battery lead 219, thence through battery B to ground G. The release magnet 136, upon energizing, attracts its armature and remains in readiness to restore the switch E when the energizing circuit through the release magnet is broken. The release relay 133, upon energizing, operates to close the springs 326 and 325 in contact,

whereby an energizing circuit is established through the release magnet 117 of the selector D and the release relay 114 of the preliminary connector C. The circuit through 5 the release magnet 117 extends from ground G* at the preliminary connector C through the release relay 114, springs 326 and 325 of the selector D, winding of the release magnet 117 to the battery lead 219, thence 10 through battery B to ground G. The circuit through the release relay magnet 114 of the preliminary connector C energizes the magnet and causes the springs 328 and 329 to close in contact, thus completing a 15 circuit through the release magnet 113. This circuit extends from ground G* through the springs 328 and 329 of the release relay 114, through the winding of the release magnet 113 to the battery lead 219, 20 thence through battery B to ground G. The release magnet 113, upon energizing, attracts its armature which, upon being released after deenergization of the release magnet 113, restores the shaft wipers 234, 25 235 and 236 and the preliminary connector C to normal position. As soon as the substation release springs 7, 8 and 9 separate, the energizing circuit of the rotary and vertical line relays 153^a and 152 of the connector F is then destroyed. As a result 30 the energizing circuit through the release magnet 164 and the back-release relay 151 is broken. Of course, when the release magnet 164 deenergizes it throws the side 35 switch of the connector back to normal position, removes the locking mechanism from the switch shaft, and produces a complete restoration of the connector switch F. It will be evident, of course, that when the 40 private wiper 155 of the connector leaves the contact point on which it has been resting, the energizing circuit through the individual bridge-cut-off relay 289 of the substation A' is also broken, which relay, of 45 course, permits the springs which it controls to return to their normal positions, thus restoring the individual line relay 293 to the control of the subscriber A'. The deenergization of the back release relay 151 50 of the selector E causes the deenergization of the release magnet 136 of the selector E. The release magnet 136, upon deenergizing, operates to restore the side switch and switch shaft of the selector E to normal condition. 55 The deenergization of the said back-release relay 151 also, of course, breaks the energizing circuit of the back-release relay 133 of the selector D, which in turn causes the deenergization of the release magnet 117 of 60 said switch D, and the deenergization of the release magnet 117 causes the full restoration of the side switch, shaft and circuits of the selector D exactly as the release magnet 136 of the switch E operates in its 65 allotted switch. It will be seen that the de-

energization of the back-release relay 133 of the selector D causes the deenergization of the release relay 114 of the preliminary connector C. When this relay deenergizes it causes the deenergization of the release 70 magnet 113, and also causes the restoration of the preliminary connector to normal position, as previously stated. The shaft wiper 236 of the preliminary connector C, upon being restored to normal, breaks the 75 energizing circuit through the individual bridge-cut-off relay 43 of the substation A, permitting its spring to again come in contact and thus placing the individual line relay 42 once more in control of said substation. The disengagement of the shaft wiper 236 of the preliminary connector C from the bank contact 239 likewise removes the guarding potential from the preliminary connector bank. Also, the separation of 80 the private shaft wiper 155 of the connector F from its bank contact removes the guarding potential protecting this bank. Thus it is seen that when the springs 7, 85 and 9 at the substation disengage, the calling subscriber restores the switching mechanism which he has employed.

The busy-release of the connector F follows as a result of the energization of the rotary line relay 153^a, if the called line is 90 busy, as follows: The said relay 153^a, upon energizing, energizes the private magnet 159, as previously described, which latter in turn presses the springs 330 and 331 into contact. As soon as the said springs 330 100 and 331 engage, the release magnet 164 is then placed in connection with the private wiper 155, since the side switch wiper 163 is now in second position, which wiper 155 has been previously rotated on a grounded 105 contact. As a result a flow of current is sent through the release magnet 164 from the grounded private wiper 155 to the side switch wiper 163, contact point 280 to the private magnet springs 330 and 331, to the 110 release magnet 164, differential relay springs 276 and 275, thence to the battery lead 219, and through battery B to ground G. The release magnet 164, upon energizing, releases the connector switch shaft and restores the connector side switch to its first 115 position, returning the vertical magnet 156 to the control of the vertical relay 152. Therefore, if the subscriber at the calling 120 station (Fig. 1) presses the signaling button 41 and grounds the vertical line conductor 30, he operates the vertical line relay 152, which latter in turn operates the vertical magnet 156. The vertical armature then raises the switch shaft so that the normal 125 post arm 332 permits the switch shaft spring 333 to come into contact with the spring 334, and the busy-signaling current is sent to the calling subscriber's station from the busy-signaling machine M. Upon hearing 130

the busy-signal the calling subscriber will understand that the desired line is in service and will release the switching apparatus by hanging up his receiver. The vertical and rotary line conductors 30 and 31 are again grounded simultaneously over circuits that have been described, whereby the vertical and rotary line relays 152 and 153^a of the connector, together with the differential relay 165, are energized at the same time. The circuits for energizing said relay have already been pointed out. It will be evident then that the line relays 152 and 153^a will carry the release springs 319 and 320 into engagement at the same time that the differential relay 165 carries the differential relay springs 275 and 276 into engagement, setting up, therefore, the energizing circuit for the release magnet 164 in series with the back-release relay 151 of the selector E and releasing the central office switches, as already explained.

From the foregoing it will be seen that all current for talking purposes is supplied to the lines through switches that are less in number than the lines, and this is true of the calling lines as well as of the called line. Current for talking purposes is supplied through the connector and over the trunking connection to the line wipers of the pre-selector or trunk-connecting switch that has seized the line of the calling subscriber. Current for talking purposes is also supplied through the connector to the called line, so that in each case, whether the line be calling or called talking current is supplied thereto from and through the line wipers that have seized the line, whether the same be calling or called. When a connection is established, it will be seen that the preselector or trunk connector is between the calling subscriber's common battery transmitter and the common battery connector that has temporarily seized the called line. All of the switches allowed to remain in the connection established for talking purposes are of the vertical and rotary motion type—that is to say, switches the line wipers of which have both vertical and rotary motion to find the idle line, whether such line be a trunk-line or a subscriber's line. The vertical motion, as described, is to find a section or sub-section, or group, while the rotary motion is to connect with a line in the selected section or sub-section or group. Thus common battery current for talking purposes is furnished to the subscribers' lines in a system in which the first-selectors are less in number than the subscribers, and in which no individual trunking switches are provided for the subscribers' lines.

What I claim as my invention is:—

1. In a telephone system, the combination of means operative under substation control to supply current for talking purposes from

the exchange or central station to the telephones of the substations thereof, a plurality of subscribers' telephone lines, a line relay normally in bridge in each line at the central station, a bridge-cut-off relay for each line, a plurality of switches common to all of said lines, but less in number than the latter, a machine having a plurality of normally open circuits controlled by said line relays, automatic means for insuring the connection of an idle switch with the said machine when a subscriber calls in, means for setting said machine in operation whenever a subscriber attempts to communicate with another subscriber, the circuits controlled by each subscriber's line relay being of such character and combined with operative means of such nature that the said machine, when set in operation, will always transmit to the idle switch a call corresponding to the number of the calling subscriber, and means whereby each idle switch, upon closing a connection to a calling subscriber's line, effects the energizing of the bridge-cut-off relay belonging to such line.

2. In a telephone system, the combination of means operative under substation control to supply current for talking purposes from the exchange or central station to the telephones of the substations thereof, a step-by-step mechanism, means under the control of the subscriber for operating such step-by-step mechanism, said mechanism including a series of contacts arranged in a circle, and a normally at rest rotatable shaft adapted to rotate always in one direction and provided with a wiper adapted to engage the said contacts, adapted always to make a complete rotation before stopping at normal.

3. In a telephone system, having lines to each of which a two digit number is assigned, the combination of means operative under substation control to supply current for talking purposes from the exchange or central station to the telephones of the substations thereof, means under the control of the calling subscriber for electrically calling his own number whenever he makes a call, said means including contacts arranged in a circle, a suitably-propelled rotary shaft provided with a wiper adapted to engage said contacts and always revolve in the same direction, and means for cutting out one or more of said contacts and for varying the number of contacts cut out to vary the number of impulses for calling.

4. In a telephone system, the combination of means operative under substation control to supply current for talking purposes from the exchange or central station to the telephones of the substations thereof, a step-by-step switching mechanism under the control of the calling subscriber for automatically transmitting electrical impulses corresponding to the digits of his own number, said

means including a plurality of circuits controlled by relays, a series of bank contacts arranged in a circle, a rotary shaft provided with a wiper adapted to engage said contacts and always revolve in the same direction, and means for cutting out one or more of said contacts to vary the number of impulses.

5. In a telephone system, the combination of means operative under substation control to supply current for talking purposes from the exchange or central station to the telephones of the substations thereof, a bank of contacts, a suitably propelled wiper adapted to travel around upon said contacts, a couple of conducting paths containing a plurality of normally closed switch points, conductors connecting said contacts with said conducting paths, each of said switch points being located intermediate of the two points at which two adjacent contacts are connected with the conducting path containing such switch point, two sets of relays for controlling said two sets of switch points, means under the control of the calling subscriber for operating one relay in each set in accordance with the number of the calling subscriber, a step-by-step switching device provided with wipers or movable switching arms connected with said conducting paths, and a plurality of step-by-step switches connected with said step-by-step switching device and adapted to be operated by the impulses transmitted by the rotation of the said first-mentioned wiper.

6. In a telephone system, the combination of means operative under substation control to supply current for talking purposes from the exchange or central station to the telephones of the substations thereof, a plurality of vertical line relays, a plurality of rotary line relays, a plurality of subscribers' lines, a line relay for each line, circuits for said vertical and rotary relays controlled by said line relays, each line relay controlling the circuit of one vertical relay and one rotary relay, according to the number of the subscriber to whom such line relay is allotted, a plurality of circuits controlled by said vertical and rotary relays, and automatic means for transmitting impulses through said last-mentioned circuits, the number of impulses transmitted each time depending upon which, if any, of said last-mentioned circuits have been opened by the energizing of any particular calling subscriber's line relay.

7. In a telephone system, the combination of means operative under substation control to supply current for talking purposes from the exchange or central station to the telephones of the substations thereof, a group of telephone lines, a plurality of switches less in number than said lines, provided with stationary banks of multiple terminals for

said lines, a trunk-line leading from each switch, and a machine for operating said switches, adapted for use only by calling subscribers in preliminarily and automatically operating said switches to close connection 70 between calling telephone lines and idle trunk-lines, provided with automatic means for skipping busy switches and stopping in operative connection with the first idle switch, said machine also provided with 75 electrical impulse-transmitting means for calling the number of the calling subscriber, to cause the selected switch to connect its trunk-line with the calling telephone line, said switches each having a set of swinging 80 wipers connected with its allotted trunk-line and adapted to coöperate with its bank of terminals in connecting the same with any of said telephone lines.

8. In a telephone system, the combination 85 of means operative under substation control to supply current for talking purposes from the exchange or central station to the telephones of the substations thereof, trunks, telephone lines to be connected with said 90 trunks, switching means for so doing, a trunk-selecting mechanism, an electrical impulse-transmitting mechanism associated with said selecting mechanism, and subscriber-controlled automatic means for causing the impulses received by said switching means from said transmitting mechanism to always correspond to a plurality of digits of the number of the calling telephone line, said switching means provided with means 95 for causing said selecting mechanism to select the next idle trunk-line each time the previously selected trunk-line is put in connection with a calling telephone line, whereby each calling subscriber always gets the 100 idle trunk-line automatically selected by the previous call.

9. In a telephone system, the combination 110 of means operative under substation control to supply current for talking purposes from the exchange or central station to the telephones of the substations thereof, trunks, means common to said trunks for automatically calling a plurality of digits of the number of a calling subscriber, and means 115 by which said calling subscriber automatically selects a trunk for the next call.

10. In a telephone system, the combination 120 of means operative under substation control to supply current for talking purposes from the exchange or central station to the telephones of the substations thereof, a number-calling device provided with a plurality of contacts, a wiper adapted to move over said contacts, and cut-out relays 125 each adapted to cut out one or more of said contacts, according to the number to be called.

11. In a telephone system, the combination 130 of means operated under substation

- control to supply current for talking purposes from the exchange or central station to the telephones of the substations thereof, an automatic number-calling mechanism 5 provided with a plurality of groups of cut-out relays, one group for each digit of the number to be called, and a set of contacts for each group, each relay adapted to cut out one or more of the contacts of the set 10 allotted to the group to which it belongs.
12. In a telephone system, the combination of means operative under substation control to supply current for talking purposes from the exchange or central station to the telephones of the substations thereof, automatic means common to a plurality of trunks for calling a plurality of digits of the number of the calling subscriber, a suitable number of telephone lines, a number 15 of trunk connections common to said lines, and automatic means for maintaining all idle lines in selective relation to the first idle trunk connection next in order after the one last in use, whereby such calling subscriber gets a preselected trunk connection. 20
13. In a telephone system, the combination of means operative under substation control to supply current for talking purposes from the exchange or central station to the telephones of the substations thereof, means common to a plurality of trunks for automatically calling a plurality of digits 25 of the number of the calling line each time a subscriber starts to make a call, located at the central station or exchange, comprising means for transmitting separate and distinct groups of electrical impulses for and corresponding to each digit of the said number, means operated by said impulses, adapted to select and connect with the calling line, and subscribers' individual line relays for controlling said impulse-transmitting means. 30
14. In a telephone system, the combination of means operative under substation control to supply current for talking purposes from the exchange or central station to the telephones of the substations thereof, trunks, an automatic numerical impulse-transmitter, an 35 automatic trunk-selecting mechanism provided with means for distinguishing between busy and idle trunks, and automatic means for maintaining said transmitter in connection only with the first idle trunk next in order after the one last in use. 40
15. In a telephone system, the combination of means operative under substation control to supply current for talking purposes from the exchange or central station to the telephones of the substations thereof, an automatic electrical impulse-transmitter provided with a wiper for making a complete revolution each time any subscriber calls, means by which calling subscribers initiate 45 the operation of said transmitter, automatic means for varying the number of impulses for different calling subscribers, and means responsive to said impulses for finding the calling subscribers. 50
16. In a telephone system, the combination of means operative under substation control to supply current for talking purposes from the exchange or central station to the telephones of the substations thereof, an automatic electrical impulse-transmitter 55 provided with a wiper for making a complete stroke or maximum movement each time any subscriber calls, means by which calling subscribers initiate the operation of said transmitter, automatic means for varying the number of impulses for different calling subscribers, and means responsive to said impulses for finding the calling subscribers. 60
17. In a telephone system, the combination of means operative under substation control to supply current for talking purposes from the exchange or central station to the telephones of the substations thereof, an automatic electrical impulse-transmitter having the same range of movement or operation each time any subscriber calls, means by which calling subscribers initiate the operation of said transmitter, automatic means for varying the number of impulses for different calling subscribers, and means responsive to said impulses for finding the calling subscribers. 65
18. In a telephone system, the combination of means operative under substation control to supply current for talking purposes from the exchange or central station to the telephones of the substations thereof, an automatic electrical impulse-transmitter provided with a series of contacts, a wiper for engaging said contacts, means for moving the wiper over all of the contacts each time any subscriber calls, means for automatically cutting out one or more of said contacts to vary the number of impulses for the different subscribers, means by which calling subscribers initiate the operation of said transmitter, and means responsive to said impulses for finding the calling subscribers. 70
19. In a telephone system, the combination of means operative under substation control to supply current for talking purposes from the exchange or central station to the telephones of the substations thereof, an automatic electrical impulse-transmitter provided with a series of contacts, a wiper for engaging said contacts, a series of relays for moving the wiper over all of the contacts each time any subscriber calls, means for automatically cutting out one or more of said contacts to vary the number of impulses for the different subscribers, means by which calling subscribers initiate the operation of said transmitter, and means responsive to said impulses for finding the calling subscribers. 75
- 130

20. In a telephone system, the combination of means operative under substation control to supply current for talking purposes from the exchange or central station to the telephones of the substations thereof, the subscribers' lines divided in groups, of a plurality of pairs of switches for each line group, each pair comprising a preselector and a corresponding first-selector, each preselector and first-selector comprising line contacts, a traveling contact device and means for moving the traveling contact device into engagement with the single line contacts, the traveling contact device of each preselector being in electrical communication with that of its companion first-selector, the line contacts of the preselectors being connected to the corresponding subscribers' lines, trunk-lines connected to the line contacts of the first-selector, an auxiliary switch common to a plurality of preselectors including a calling device for transmitting impulses in accordance with the digits of the calling number and coupled for a call with one of said preselectors and working simultaneously with the same, a calling relay for each subscriber arranged to set in action said auxiliary switch and the means for moving the traveling contact device of an idle preselector, and means actuated at the calling station for operating the traveling contact device of the corresponding first-selector.
21. In a telephone system, the combination of means operative under substation control to supply current for talking purposes from the exchange or central station to the telephones of the substations thereof, the subscribers' lines divided in groups, a plurality of preselectors and first-selectors for each line group arranged in pairs, each preselector and first-selector comprising line contacts, a traveling contact device and means for moving the traveling contact device, the traveling contact device of each preselector being in electrical communication with that of its corresponding first-selector, the subscribers' lines of the group being connected to the line contacts of the preselectors, trunk-lines connected to the line contacts of the first-selectors, an auxiliary switch common to a plurality of preselectors, coupled for a call with one of said preselectors and working simultaneously with the same, a calling relay for each subscriber's line arranged to set in action said auxiliary switch and an idle preselector upon a call, means at the subscribers' stations to actuate automatically the corresponding calling relay when the receiver is taken up, means at the subscribers' stations for operating and controlling the first-selector and for making the final connection over the selected trunk-line, and means controlled by the calling subscriber to release the entire connection at any time.
22. In a telephone system, the combination of means operative under substation control to supply current for talking purposes from the exchange or central station to the telephones of the substations thereof, the subscribers' lines divided in groups, of a plurality of pairs of switches for each line group, each pair comprising a preselector and corresponding first-selector, each preselector and first-selector comprising line contacts, a traveling contact device and means for moving the traveling contact device into engagement with the single line contacts, the traveling contact device of each preselector being in electrical communication with that of its companion first-selector, the line contacts of the preselector being connected to the corresponding subscribers' lines, trunk-lines connected to the line contacts of the first-selectors, an auxiliary switch common to a plurality of preselectors including a calling device for transmitting impulses in accordance with the digits of the calling number and coupled for a call with one of said preselectors and working simultaneously with the same, a calling relay for each subscriber arranged to set in action said auxiliary switch and the means for moving the traveling contact device of an idle preselector, and to stop the said preselector upon the arrival of its traveling contact device at the contacts of the calling subscriber's line, and means at the calling station for controlling the traveling contact device of the corresponding first-selector.
23. In a telephone system, the combination of means operative under substation control to supply current for talking purposes from the exchange or central station to the telephones of the substations thereof, the subscribers' lines divided in groups, of a plurality of pairs of switches for each line group, each pair comprising a preselector and a corresponding first-selector, each preselector and first-selector comprising line contacts, a traveling contact device and means for moving the traveling contact device into engagement with the single line contacts, the traveling contact device of each preselector being in electrical communication with that of its companion first-selector, the line contacts of the preselectors being connected to the corresponding subscribers' lines, trunk-lines connected to the line contacts of the first-selectors, an auxiliary switch common to a plurality of preselectors including a calling device for transmitting impulses in accordance with the digits of the calling number and coupled for a call with one of said preselectors and working simultaneously with the same, a calling relay for each subscriber, a common

calling relay arranged to be actuated by any subscriber's calling relay and to set in action said auxiliary switch and the means for moving the traveling contact device of an idle preselector, and means actuated at the calling station for operating the traveling contact device of the corresponding first-selector.

24. In a telephone system, the combination of means operative under substation control to supply current for talking purposes from the exchange or central station to the telephones of the substations thereof, the subscribers' lines divided in groups, of a plurality of switches for each line group, said switches being arranged in pairs, each pair comprising a preselector and a first-selector, each preselector and its first-selector comprising line contacts, a traveling contact device arranged to engage said line contacts, the traveling contact device of each preselector being in electrical communication with that of the corresponding first-selector, the line contacts of each preselector being connected to the corresponding subscribers' lines, trunk-lines connected to the line contacts of the first-selectors, means for moving said traveling contact devices, an auxiliary switch common to a plurality of preselectors, coupled for a call with one of said preselectors and working simultaneously with the same, a calling relay for each subscriber arranged to set in action the means for moving the traveling contact device of a preselector, a cut-off relay for each subscriber arranged to cut out the calling subscriber's calling relay when the preselector is set on the calling line, means at the calling station for controlling the traveling contact device of the first-selector, means operated over the selected trunk-line for making the final connection to the desired subscriber, and means controlled by the calling subscriber to release the entire connection at any time.

25. In a telephone system, the combination of means operative under substation control to supply current for talking purposes from the exchange or central station to the telephones of the substations thereof, the subscribers' lines divided in groups, of a plurality of switches for each line group, said switches being arranged in pairs, each pair comprising a preselector and a corresponding first-selector, each preselector and its first-selector comprising line contacts, a traveling contact device arranged to engage said line contacts, the traveling contact device of each preselector being in electrical communication with that of the corresponding first-selector, the line contacts of each preselector being connected to the corresponding subscribers' lines, trunk-lines connected to the line contacts of the first-selectors.

tors, and auxiliary switch common to a plurality of preselectors, coupled for a call with one of said preselectors and working simultaneously with the same, means for moving said traveling contact devices, a calling relay for each subscriber arranged to set in action said auxiliary switch and the means for moving the traveling contact device of a preselector, a cut-off relay for each subscriber arranged to cut out the called subscriber's calling relay, means actuated at the calling station for controlling the traveling contact device of the first-selector, means operated over the selected trunk-line for making the final connection to the desired subscriber, and means controlled by the calling subscriber to release the entire connection at any time.

26. In a telephone system, the combination of means operative under substation control to supply current for talking purposes from the exchange or central station to the telephones of the substations thereof, the subscribers' lines divided in groups, of a plurality of switches for each line group, said switches being arranged in pairs, each pair comprising a preselector and a first-selector, each preselector and its first-selector comprising line contacts, a traveling contact device of each preselector being in electrical communication with that of the corresponding first-selector, the line contacts of each preselector being connected to the corresponding subscribers' lines, trunk-lines connected to the line contacts of the first-selectors, means for moving said traveling contact devices, an auxiliary switch common to a plurality of preselectors including a calling device for transmitting impulses in accordance with the digits of the calling number and coupled for a call with one of said preselectors and working simultaneously with the same, and a pair of relays for each subscriber's line, each pair comprising a calling and a cut-off relay, the calling relay being arranged to set in action said auxiliary switch and an idle preselector upon a call, the cut-off relay being arranged to cut out its calling relay when the corresponding subscriber's line is occupied.

27. In a telephone system, the combination of means operative under substation control to supply current for talking purposes from the exchange or central station to the telephones of the substations thereof, the subscribers' lines divided in groups, of a plurality of preselectors and first-selectors for each line group, each comprising line contacts, a traveling contact device arranged to engage its line contacts, and means for moving the traveling contact device, the traveling contact device of each preselector being in electrical communication with that of one of the first-selectors, the contacts of

the preselectors being connected to the corresponding subscribers' lines, trunk-lines connected in multiple to the first-selectors, an auxiliary switch common to a plurality of 5 preselectors, coupled for a call with one of said preselectors and arranged to drive its traveling contact device to the contacts of the calling subscriber's line, a preselector finder controlled by the preselectors and arranged 10 to couple an idle preselector for the next call with said auxiliary switch, means actuated at the calling station for moving the traveling contact device of the first-selector, means operated over said trunk-lines for 15 making the final connection between subscribers' lines, and means controlled by the calling subscriber to release the entire connection at any time.

28. In a telephone system, the combination 20 of means operative under substation control to supply current for talking purposes from the exchange or central station to the telephones of the substations thereof, the subscribers' lines divided in groups and 25 in sub-groups, and for each line group local circuits equal in number to the number of the sub-groups; for each line group a plurality of preselectors, each comprising subscribers' line contacts arranged in series 30 corresponding to the sub-groups, a traveling contact device and means for moving the traveling contact device to the series of contacts and along these, a calling relay in each subscriber's line arranged to set in action 35 an idle preselector upon a call and to alter the condition of the local circuit of the sub-group to which its line belongs; for each line group a common auxiliary switch coupled with an idle preselector ready for a 40 call and working synchronously with the preselector and arranged to stop the traveling contact device of the preselector at the series of contacts of the calling subscriber's sub-group and for causing said traveling 45 contact device to come over the contacts of the calling subscriber's line.

29. In a telephone system, the combination 50 of means operative only after the called line is found for supplying talking current from the exchange or central station to the subscribers' telephones at the substations thereof, a switching apparatus comprising telephone lines, a plurality of switches, each provided with electro-magnetically-actuated 55 operating means, electro-magnetically-actuated electrical impulse-transmitting means for operating said switches, individual line relays for starting the operation of said impulse-transmitting means, and automatic means for electrically connecting the 60 said impulse-transmitting means with the said operating means of any switch, and for disconnecting it therefrom, whereby said impulse-transmitting means may be employed for operating any switch without in-

terfering with its subsequent use in operating other switches while the said operated switch remains in use.

30. In a telephone system, the combination 70 of means operative only after the called line is found for supplying talking current from the exchange or central station to the subscribers' telephones at the substations thereof, a group of subscribers' lines, a plurality of switches common to said lines, but less in 75 number than the latter, trunk-lines leading from said switches, other switches in which the said trunk-lines terminate, a normally at rest switch-operating machine common to all of said first-mentioned switches, and individual relay means under the control of the subscribers for causing said machine to operate said first-mentioned switches, whereby the calling subscriber may connect his line with one of said trunk-lines before operating 85 one of said other switches in accordance with the first digit of the called number.

31. In a telephone system, the combination 90 of means operative only after the called line is found for supplying talking current from the exchange or central station to the subscribers' telephones at the substations thereof, a plurality of subscribers' telephone lines, a line relay normally in bridge in each line at the central station, a bridge-cut-off 95 relay for each line, a plurality of switches common to all of said lines, but less in number than the latter, a machine having a plurality of normally open circuits controlled by said line relays, automatic means for 100 insuring the connection of an idle switch with the said machine when a subscriber calls in, means for setting said machine in operation whenever a subscriber attempts to communicate with another subscriber, the 105 circuits controlled by each subscriber's line relay being of such character and combined with operative means of such nature that the said machine, when set in operation, will always transmit to the idle switch a call 110 corresponding to the number of the calling subscriber, and means whereby each idle switch, upon closing a connection to a calling subscriber's line, effects the energizing of the bridge-cut-off relay belonging to such line. 115

32. In a telephone system, the combination 120 of means operative only after the called line is found for supplying talking current from the exchange or central station to the subscribers' telephones at the substations thereof, a step-by-step mechanism, means under the control of the subscriber for operating such step-by-step mechanism, said mechanism including a series of contacts arranged in a circle, and a normally at rest rotatable 125 shaft adapted to rotate always in one direction and provided with a wiper adapted to engage the said contacts, adapted always to make a complete rotation before stopping at normal.

33. In a telephone system, the combination of means operative only after the called line is found for supplying talking current from the exchange or central station to the subscribers' telephones at the substations thereof, means under the control of the calling subscriber for electrically calling his own number, said means including contacts arranged in a circle, a suitably propelled rotary shaft provided with a wiper adapted to engage said contacts and always revolve in the same direction, and means for cutting out one or more of said contacts to vary the number of impulses.
34. In a telephone system, the combination of means operative only after the called line is found for supplying talking current from the exchange or central station to the subscribers' telephones at the substations thereof, step-by-step switching mechanism under the control of the calling subscriber for automatically transmitting electrical impulses corresponding to the digits of his own number, said means including a plurality of circuits controlled by relays, a series of bank contacts arranged in a circle, a rotary shaft provided with a wiper adapted to engage said contacts and always revolve in the same direction, and means for cutting out one or more of said contacts to vary the number of impulses.
35. In a telephone system, the combination of means operative only after the called line is found for supplying talking current from the exchange or central station to the subscribers' telephones at the substations thereof, a bank of contacts, a suitably propelled wiper adapted to travel around upon said contacts, a couple of conducting paths containing a plurality of normally-closed switch points, conductors connecting said contacts with said conducting paths, each of said switch points being located intermediate of the two points at which two adjacent contacts are connected with the conducting path containing such switch point, two sets of relays for controlling said two sets of switch points, means under the control of the calling subscriber for operating one relay in each set in accordance with the number of the calling subscriber, a step-by-step switching device provided with wipers or movable switching arms connected with said conducting paths, and a plurality of step-by-step switches connected with said step-by-step switching device and adapted to be operated by the impulses transmitted by the rotation of the said first-mentioned wiper.
36. In a telephone system, the combination of means operative only after the called line is found for supplying talking current from the exchange or central station to the subscribers' telephones at the substations thereof, a plurality of vertical line relays, a plurality of rotary line relays, a plurality of subscribers' lines, a line relay for each line, circuits for said vertical and rotary relays controlled by said line relays, each line relay controlling the circuit of one vertical relay and one rotary relay, according to the number of the subscriber to whom such line relay is allotted, a plurality of circuits controlled by said vertical and rotary relays, and automatic means for transmitting impulses through said last-mentioned circuits, the number of impulses transmitted each time depending upon which, if any, of said last-mentioned circuits have been opened by the energizing of any particular calling subscriber's line relay.
37. In a telephone system, the combination of means operative only after the called line is found for supplying talking current from the exchange or central station to the subscribers' telephones at the substations thereof, a group of telephone lines, a plurality of switches less in number than said lines, provided with stationary banks of multiple terminals for said lines, a trunk-line leading from each switch, and a machine for operating said switches, adapted for use only by calling subscribers in preliminarily and automatically operating said switches to close connection between calling telephone lines and idle trunk-lines, provided with automatic means for skipping busy switches and stopping in operative connection with the first idle switch, said machine also provided with electrical impulse-transmitting means for calling the number of the calling subscriber, to cause the selected switch to connect its trunk-line with the calling telephone line, said switches each having a set of swinging wipers connected with its allotted trunk-line and adapted to coöperate with its bank of terminals in connecting the same with any of said telephone lines.
38. In a telephone system, the combination of means operative only after the called line is found for supplying talking current from the exchange or central station to the subscribers' telephones at the substations thereof, a number calling device provided with a plurality of contacts, a wiper adapted to move over said contacts, and cut-out relays each adapted to cut out one or more of said contacts, according to the number to be called.
39. In a telephone system, the combination of means operative only after the called line is found for supplying talking current from the exchange or central station to the subscribers' telephones at the substations thereof, an automatic number-calling mechanism provided with a plurality of groups of cut-out relays, one group for each digit of the number to be called, and a set of contacts for each group, each relay adapted to cut out one or more of the contacts.

tacts of the set allotted to the group to which it belongs.

40. In a telephone system, the combination of means operative only after the called line is found for supplying talking current from the exchange or central station to the subscribers' telephones at the substations thereof, an automatic electrical impulse-transmitter provided with a wiper for making a complete revolution each time any subscriber calls, means by which calling subscribers initiate the operation of said transmitter, automatic means for varying the number of impulses for different calling subscribers, and means responsive to said impulses for finding the calling subscribers.

41. In a telephone system, the combination of means operative only after the called line is found for supplying talking current from the exchange or central station to the subscribers' telephones at the substations thereof, an automatic electrical impulse-transmitter provided with a series of contacts, a wiper for engaging said contacts, means for moving the wiper over all of the contacts each time any subscriber calls, means for automatically cutting out one or more of said contacts to vary the number of impulses for the different subscribers, means by which calling subscribers initiate the operation of said transmitter, and means responsive to said impulses for finding the calling subscribers.

42. In a telephone system, the combination of means operative only after the called line is found for supplying talking current from the exchange or central station to the subscribers' telephones at the substations thereof, an automatic electrical impulse-transmitter provided with a series of contacts, a wiper for engaging said contacts, a series of relays for moving the wiper over all of the contacts each time any subscriber calls, means for automatically cutting out one or more of said contacts to vary the number of impulses for the different subscribers, means by which calling subscribers initiate the operation of said transmitter, and means responsive to said impulses for finding the calling subscribers.

43. In a telephone system, the combination of means operative only after the called line is found for supplying talking current from the exchange or central station to the subscribers' telephones at the substations thereof, the subscribers' lines divided in groups, of a plurality of pairs of switches for each line group, each pair comprising a preselector and a corresponding first-selector, each preselector and first-selector comprising line contacts, a traveling contact device and means for moving the traveling contact device into engagement with the single line contacts, the traveling contact device of each preselector being in electrical

communication with that of its companion first-selector, the line contacts of the preselectors being connected to the corresponding subscribers' lines, trunk-lines connected to the line contacts of the first-selector, an auxiliary switch common to a plurality of preselectors including a calling device for transmitting impulses in accordance with the digits of the calling number and coupled for a call with one of said preselectors and working simultaneously with the same, a calling relay for each subscriber arranged to set in action said auxiliary switch and the means for moving the traveling contact device of an idle preselector, and means actuated at the calling station for operating the traveling contact device of the corresponding first-selector.

44. In a telephone system, the combination of means operative only after the called line is found for supplying talking current from the exchange or central station to the subscribers' telephones at the substations thereof, the subscribers' lines divided in groups, a plurality of preselectors and first-selectors for each line group arranged in pairs, each preselector and first-selector comprising line contacts, a traveling contact device and means for moving the traveling contact device, the traveling contact device of each preselector being in electrical communication with that of its corresponding first-selector, the subscribers' lines of the group being connected to the line contacts of the preselectors, trunk-lines connected to the line contacts of the first-selectors, an auxiliary switch common to a plurality of preselectors, coupled for a call with one of said preselectors and working simultaneously with the same, a calling relay for each subscriber's line arranged to set in action said auxiliary switch and an idle preselector upon a call, means at the subscribers' stations to actuate automatically the corresponding calling relay when the receiver is taken up, means at the subscribers' stations for operating and controlling the first-selector and for making the final connection over the selected trunk-line and means controlled by the calling subscriber to release the entire connection at any time.

45. In a telephone system, the combination of means operative only after the called line is found for supplying talking current from the exchange or central station to the subscribers' telephones at the substations thereof, the subscribers' lines divided in groups, of a plurality of pairs of switches for each line group, each pair comprising a preselector and corresponding first-selector, each preselector and first-selector comprising line contacts, a traveling contact device and means for moving the traveling contact device into engagement with the single line contacts, the traveling contact device of each pre-

lector being in electrical communication with that of its companion first-selector, the line contacts of the preselector being connected to the corresponding subscribers' lines, trunk-lines connected to the line contacts of the first-selectors, an auxiliary switch common to a plurality of preselectors, including a calling device for transmitting impulses in accordance with the digits 5 of the calling number and coupled for a call with one of said preselectors and working simultaneously with the same, a calling relay for each subscriber arranged to set in action said auxiliary switch and the means 10 for moving the traveling contact device of an idle preselector, and to stop the said preselector upon the arrival of its traveling contact device at the contacts of the calling subscriber's line, and means at the calling 15 station for controlling the traveling contact device of the corresponding first-selector.

46. In a telephone system, the combination of means operative only after the called line is found for supplying talking current 20 from the exchange or central station to the subscribers' telephones at the substations thereof, the subscribers' lines divided in groups, of a plurality of pairs of switches for each line group, each pair comprising a preselector and a corresponding first-selector, each preselector and first-selector comprising line contacts, a traveling contact device and means for moving the traveling contact device into engagement with the 25 single line contacts, the traveling contact device of each preselector being in electrical communication with that of its companion first-selector, the line contacts of the preselectors being connected to the corresponding 30 subscribers' lines, trunk-lines connected to the line contacts of the first-selectors, an auxiliary switch common to a plurality of preselectors including a calling device for transmitting impulses in accordance with the digits 35 of the calling number and coupled for a call with one of said preselectors and working simultaneously with the same, a calling relay for each subscriber, a common calling relay arranged to be actuated by 40 any subscriber's calling relay and to set in action said auxiliary switch and the means for moving the traveling contact device of an idle preselector, and means actuated at the calling station for operating the traveling contact device of the corresponding 45 first-selector.

47. In a telephone system, the combination of means operative only after the called line is found for supplying talking current 50 from the exchange or central station to the subscribers' telephones at the substations thereof, the subscribers' lines divided in groups, of a plurality of switches for each line group, said switches being arranged in 55 pairs, each pair comprising a preselector and a first-selector, each preselector and its first-selector comprising line contacts, a traveling contact device arranged to engage said line contacts, the traveling contact device of each preselector being in electrical communication with that of the corresponding first-selector, the line contacts of each preselector being connected to the corresponding subscribers' lines, trunk-lines connected to the line contacts of the first-selectors, an auxiliary switch common to a plurality of preselectors, coupled for a call with one of said preselectors and working simultaneously with the same, means for moving said traveling contact devices, a calling relay for each subscriber arranged to set in action said auxiliary switch and the means for moving the traveling contact device of a preselector, a cut-off relay for each subscriber arranged to cut out the calling subscriber's calling relay when the preselector is set on the calling line, means at the calling station for controlling the traveling contact device of the first-selector, means operated over the selected trunk-line for making the final connection to the desired subscriber, and means controlled by the calling subscriber to release the entire connection at any time.

48. In a telephone system, the combination of means operative only after the called line is found for supplying talking current 90 from the exchange or central station to the subscribers' telephones at the substations thereof, the subscribers' lines divided in groups, of a plurality of switches for each line group, said switches being arranged in pairs, each pair comprising a preselector and a corresponding first-selector, each preselector and its first-selector comprising line contacts, a traveling contact device arranged to engage said line contacts, the traveling contact device of each preselector being in electrical communication with that of the corresponding first-selector, the line contacts of each preselector being connected to the corresponding subscribers' lines, trunk-lines connected to the line contacts of the first-selectors, an auxiliary switch common to a plurality of preselectors, coupled for a call with one of said preselectors and working simultaneously with the same, means for moving said traveling contact devices, a calling relay for each subscriber arranged to set in action said auxiliary switch and the means for moving the traveling contact device of a preselector, a cut-off relay for each subscriber arranged to cut out the called subscriber's calling relay, means actuated at the calling station for controlling the traveling contact device of the first-selector, means operated over the selected trunk-line for making the final connection to the desired subscriber, and means controlled by the calling subscriber to release the entire connection at any time.

49. In a telephone system, the combination of means operative only after the called line is found for supplying talking current from the exchange or central station to the subscribers' telephones at the substations thereof, the subscribers' lines divided in groups, of a plurality of switches for each line group, said switches being arranged in pairs, each pair comprising a preselector and a first-selector, each preselector and its first-selector comprising line contacts, a traveling contact device of each preselector being in electrical communication with that of the corresponding first-selector, the line contacts of each preselector being connected to the corresponding subscribers' lines, trunk-lines connected to the line contacts of the first-selectors, means for moving said traveling contact devices, an auxiliary switch common to a plurality of preselectors including a calling device for transmitting impulses in accordance with the digits of the calling number and coupled for a call with one of said preselectors and working simultaneously with the same, and a pair of relays for each subscriber's line, each pair comprising a calling and a cut-off relay, the calling relay being arranged to set in action said auxiliary switch and an idle preselector upon a call, the cut-off relay being arranged to cut out its calling relay when the corresponding subscriber's line is occupied.
50. In a telephone system, the combination of means operative only after the called line is found for supplying talking current from the exchange or central station to the subscribers' telephones at the sub-stations thereof, the subscribers' lines divided in groups and in sub-groups, and for each line group local circuits equal in number to the number of the sub-groups; for each line group a plurality of preselectors, each comprising subscribers' line contacts arranged in series corresponding to the sub-groups, a traveling contact device and means for moving the traveling contact device to the series of contacts and along these, a calling relay in each subscriber's line arranged to set in action an idle preselector upon a call and to alter the condition of the local circuit of the sub-group to which its line belongs; for each line group a common auxiliary switch coupled with an idle preselector ready for a call and working synchronously with the preselector and arranged to stop the traveling contact device of the preselector at the series of contacts of the calling subscriber's sub-group and for causing said traveling contact device to come over the contacts of the calling subscriber's line.
51. In a telephone system having lines to each of which a different number is as-
- signed, the combination of means operative under substation control to supply current for talking purposes from the exchange or central station to the telephones of the substations thereof, an impulse transmitter and controller device common to said lines, means under the control of the calling subscriber for setting the controller section to cause the transmitter section to always call the number of the calling subscriber whenever he makes a call, and progressively movable switches responsive to said device to find the calling line.
52. In a telephone system having lines to each of which a different number is assigned, an impulse transmitter and controller device common to said lines, means under the control of the calling subscriber for setting the controller section to cause the transmitter section to always call the number of the calling subscriber whenever he makes a call, means normally at rest and responsive to said device for finding and seizing the calling line, suitable instrumentalities for extending connection to the called line, and a central battery for supplying talking current to the calling line.
53. In a telephone system having lines to each of which a different number is assigned, an impulse transmitter and controller device common to said lines, means under the control of the calling subscriber for setting the controller section to cause the transmitter section to always call the number of the calling subscriber whenever he makes a call, means normally at rest and responsive to said device for finding and seizing the calling line, suitable instrumentalities for extending connection to the called line, and a central battery for supplying talking current to the called line.
54. In a telephone system having lines to each of which a different number is assigned, an impulse transmitter and controller device common to said lines, means under the control of the calling subscriber for setting the controller section to cause the transmitter section to always call the number of the calling subscriber whenever he makes a call, means normally at rest and responsive to said device for finding and seizing the calling line, and centrally located instrumentalities for supplying current over the calling and called lines to the substations thereof for talking purposes.
55. In a telephone system having lines to each of which a different number is assigned, an impulse transmitter and controller device common to said lines, means under the control of the calling subscriber for setting the controller section to cause the transmitter section to always call the number of the calling subscriber whenever he makes a call, means responsive to the said device for se-

lecting the calling line, and a central battery for supplying current over the line to the substations thereof for talking purposes.

56. In a telephone system having lines to each of which a different number is assigned, the combination of means operative under substation control to supply current for talking purposes from the exchange or central station to the telephones of the substations thereof, an impulse transmitter and controller device common to said lines, means under the control of the calling subscriber comprising a relay individual to the line for setting the controller section to cause the transmitter section to always call the number of the calling subscriber whenever he makes a call, and a progressively movable switch responsive to said impulse sender to find the calling line.

57. In a telephone system having lines to each of which a different number is assigned, an impulse transmitter and controller, means under the control of the calling subscriber comprising a relay individual to the line for setting the controller section to cause the transmitter section to always call the number of the calling subscriber whenever he makes a call, means normally at rest and responsive to said device for finding and seizing the calling line, suitable instrumentalities for extending connection to the called line, and a central battery for supplying talking current to the calling line.

58. In a telephone system having lines to each of which a different number is assigned, an impulse transmitter and controller device common to said lines, means under the control of the calling subscriber comprising a relay individual to the line for setting the controller section to cause the transmitter section to always call the number of the calling subscriber whenever he makes a call, means normally at rest and responsive to said device for finding and seizing the calling line, suitable instrumentalities for extending connection to the called line, and a central battery for supplying talking current to the calling line.

59. In a telephone system having lines to each of which a different number is assigned, an impulse transmitter and controller device common to said lines, means under the control of the calling subscriber comprising a relay individual to the line for setting the controller section to cause the transmitter section to always call the number of the calling subscriber whenever he makes a call, means normally at rest and responsive to said device for finding and seizing the calling line, and centrally located instrumentalities for supplying current over the calling and called lines to the substations thereof for talking purposes.

60. In a telephone system having lines to

each of which a different number is assigned, an impulse transmitter, a transmitter controller, means under the control of the calling subscriber comprising a relay individual to the line for setting said controller to cause the transmitter to always call the number of the calling subscriber whenever he makes a call, means responsive to the said transmitter for selecting the calling line, and a central battery for supplying current over the line to the substations thereof for talking purposes.

61. In a telephone system, an automatic electrical impulse-transmitter provided with a wiper for making a complete revolution each time any subscriber calls, means by which calling subscribers initiate the operation of said transmitter, automatic means for varying the number of impulses for different calling subscribers, means responsive to said impulses for finding the calling subscribers, and a central source of battery for supplying current to said subscribers for talking purposes.

62. In a telephone system, an automatic electrical impulse-transmitter provided with a wiper for making a complete stroke or maximum movement each time any subscriber calls, means by which calling subscribers initiate the operation of said transmitter, automatic means for varying the number of impulses for different calling subscribers, means responsive to said impulses for finding the calling subscribers, and a central source of battery for supplying current to said subscribers for talking purposes.

63. In a telephone system, an automatic electrical impulse-transmitter having the same range of movement or operation each time any subscriber calls, means by which calling subscribers initiate the operation of said transmitter, automatic means for varying the number of impulses for different calling subscribers, means responsive to said impulses for finding the calling subscribers, and a central source of battery for supplying current to said subscribers for talking purposes.

64. In a telephone system, an automatic electrical impulse-transmitter provided with a series of contacts, a wiper for engaging said contacts, means for moving the wiper over all of the contacts each time any subscriber calls, means for automatically cutting out one or more of said contacts to vary the number of impulses for the different subscribers, means by which calling subscribers initiate the operation of said transmitter, means responsive to said impulses for finding the calling subscribers, and a central source of battery for supplying current to said subscribers for talking purposes.

65. In a telephone system, an automatic

electrical impulse-transmitter provided with a series of contacts, a wiper for engaging said contacts, a series of relays for moving the wiper over all of the contacts each time 5 any subscriber calls, means for automatically cutting out one or more of said contacts to vary the number of impulses for the different subscribers, means by which calling subscribers initiate the operation of 10 said transmitter, means responsive to said impulses for finding the calling subscribers, and a central source of battery for supplying current to said subscribers for talking purposes.

15 66. In a telephone system, a calling device, a plurality of magnets, a series circuit passing through contacts controlled by said magnets, means whereby any two of said magnets may be operated to thereby control 20 the impulses sent out by said calling device,

and a central battery for supplying current to calling and called subscribers' lines for talking purposes, substantially as described.

67. In a telephone system, means for establishing a connection between a calling 25 and a called line, said means comprising a finder switch, a selector switch and a connector switch, all of said switches having motion in two intersecting planes, one motion of each of said switches controlled by 30 a predetermined number of impulses, and a central battery for supplying current to calling and called subscribers' lines for talking purposes.

Signed by me at Chicago, Cook county, 35 Illinois, this 20 day of March, 1908.

JOHN ERICKSON.
